UNITED STATES PATENT OFFICE.

TALBOT G. MARTIN, OF CHICAGO, ILLINOIS, ASSIGNOR, BY MESNE ASSIGNMENTS, TO FIRST TRUST AND SAVINGS BANK, TRUSTEE, OF CHICAGO, ILLINOIS.

TELEPHONE-EXCHANGE SYSTEM.

1,194,339.

Specification of Letters Patent.

Patented Aug. 8, 1916.

Application filed April 17, 1906, Serial No. 312,156. Renewed October 14, 1914. Serial No. 866,726.

To all whom it may concern:

Be it known that I, TALBOT G. MARTIN, a citizen of the United States of America, and resident of Chicago, Cook county, Illinois, 5 have invented a certain new and useful Improvement in Telephone-Exchange Systems, of which the following is a specification.

My invention relates to telephone systems in general, but more particularly to automatic or semi-automatic telephone systems, and especially to automatic telephone systems in which electrically-propelled and step-by-step-actuated switching machinery is employed at the exchange or central station for completing connection between calling and called subscribers' lines.

As herein described and illustrated, my invention is shown in connection with a system in which selectors and connectors 20 are employed, and in which the current for charging the subscribers' transmitters is supplied from a common battery or other centralized source of talking current, the same source being also employed for furnishing 25 the electrical current for operating the said selectors and connectors. For the broader purposes of my invention, however, the subscriber-controlled and automatic switching machinery for connecting calling lines with 30 called lines may be of any suitable, known or approved character, and the current for charging the subscribers' transmitters may be obtained from any suitable source or sources, such as local batteries at the subscribers' substations.

As will hereinafter more fully appear, my invention is in certain respects an improvement on the automatic common battery telephone system described in my Patent No. 1,185,521, granted May 30, 1916. It will also be seen that in certain respects my invention is in the nature of an improvement on the general type of connector disclosed in Patent No. 815,176, granted March 45 13, 1906, to Keith, Erickson and Erickson. For the purpose of illustrating my invention the selectors herein shown and described may be of the general type disclosed in Patent No. 815,321, granted March 13, 1906, 50 to Keith, Erickson and Erickson.

Generally stated, the object of my invention is the provision of an improved and highly efficient telephone system, preferably of the automatic or semi-automatic type, of 55 such character that it will afford improved

and satisfactory telephone service to the subscribers thereof, at the same time taking into account that a reasonably low cost of installation and maintenance is always, in matters of this kind, an important consideration.

Special objects of my invention are the provision of connectors or other automatic switching machinery having means for automatically applying the ringing or call-signal current to the called subscriber's line as soon as the connection between the two lines is fully established, whereby the calling subscriber merely calls the desired number, and is not required to operate a ringing-key or button after establishing connection with the called line; the provision of such a construction and arrangement as will permit a connector to lock itself on the called line, regardless of whether the latter is busy or idle, and until the calling subscriber hangs up his telephone, during which time the connector either rings the called subscriber until the latter answers, or in the event that the called line is busy automatically transmits a busy signal to the calling subscriber, the arrangement also being such that the connector can thus lock itself on a busy line without interfering with the conversation already being carried on over such line, and without permitting the calling subscriber to listen-in or overhear such conversation; the provision of an improved trunk-releasing arrangement involving a differential-relay in the talking circuit, preferably at the 90 called side of the condensers or other inductive connections which are associated with the connector and which are located in the talking circuit for the purpose of dividing the same into two inductively-connected portions, as will hereinafter more fully appear; the provision of an improved arrangement whereby the ringing-generator can also be employed for supplying the current necessary for transmitting a busy signal to the calling subscriber when the called line is busy or already occupied; and the provision of certain details, combinations and features of improvement tending to increase the general efficiency and serviceability of 95 a telephone system of this particular character.

To the foregoing and other useful ends, as will hereinafter more fully appear, and as will be apparent to those skilled in the 100 105 110

art, my invention consists in matters hereinafter set forth and claimed.

In the accompanying drawings, Figure 1 is a diagram of a calling subscriber's line 5 and the called subscriber's line and the other connecting apparatus comprising the first-selector A of the calling line, a connector C common to the subscribers, and a first-selector A¹ of the called line. Fig. 2 is not only 10 a diagrammatic view of the first selector A, but a perspective as well, showing the arrangement of the relative parts about the switch-frame, which latter is not shown. Fig. 3 is a similar view of a connector- 15 switch. Fig. 4 illustrates changes to be made in the connector circuits when the said connector is used in a very small exchange, in which case the calling subscriber's line-conductors are connected directly to the 20 connector.

The use of first-selectors and even of second-selectors and other switches commonly used in systems of the general type herein described is not essential. Subscribers may 25 be provided with connectors only, if necessary, as will be hereinafter more fully described.

The substation equipments employed in connection with common battery systems of 30 the nature in question are all of a well-known and suitable type. Substation #100, for example, is at once recognized by the peculiar switch-hook 2 which is made with a number of cam-like arms 3, 4, 5 and 35 6. The primary circuit at said station comprises the main line-conductors in series, and contains the primary winding 7 of the induction-coil 8, a transmitter 9, a couple of springs 10 and 11 through the medium of 40 which the said circuit is maintained closed or opened, depending upon whether the hook is up or down. Said hook is pivoted by a screw 12, and is forced to rise whenever the weight of the receiver 45 13 is removed from it, by a suitable switch-hook-spring not shown. The secondary circuit comprises the said receiver 13 in series with the secondary winding 14 of the induction-coil 8 in a permanently closed local 50 circuit. The ringer circuit at said substation includes the ringer 15, the ringer circuit springs 16 and 17, and the condenser 18. This circuit, while the switch-hook is down, is closed by the cam-arm 4 that presses the 55 ringer circuit springs 16 and 17 into contact, and is normally bridged across the main line. While the hook is up, however, the said bridge is open, because the said springs 16 and 17 spring apart after the 60 cam-arm 4 is removed from the spring 16. The cam-arm 6 controls the continuity of a ground circuit between the so-called ground-post 19 and the ground terminal G¹, through the medium of two springs 20 and 21 that 65 are included in said circuit. The substation

has three other springs 22, 23 and 24 which are known as the release-springs and by means of which the main line-conductors may be grounded simultaneously for the purpose of restoring the exchange apparatus. When the switch-hook is depressed, as it descends, the said release-springs are forced together by the cam-arm 3, which latter then engages the laterally projecting extremity 25 upon the spring 24. The engaging portions of the cam 3 and spring 24 are constructed with their surfaces at an angle to each other, so that when the hook goes down one surface of the projection 25 is engaged, and when it rises the opposite 80 surface comes into use. In this way, when the hook goes down, the spring 24 is forced onto the springs 23 and 22, and when the hook rises it is shoved in the opposite direction. Therefore, at the limit of each stroke 85 of the hook the cam-arm 3 clears the spring 24. The calling device employed by the subscriber comprises two push-buttons 26 and 27, two contact-points 28 and 29, two springs 30 and 31 and the so-called ground-post 19. The spring 30 and contact 28 are normally in contact, as well as the spring 31 and contact 29. But when the button 26 is pressed the spring 30 is separated from the contact-point 28 and connected with the 90 ground-post 19, and when the button 27 is pressed the second spring 31 is pressed onto the same ground-post, after said spring leaves the contact-point 29.

The first-selector may be of any suitable 100 or approved type. In Fig. 2, for instance, is shown the first-selector A with the bank 32 of trunk-line terminals beneath it, while the private-bank 33 is located just above the line-bank. The switch-shaft 34 is vertically disposed on the front of the switch-frame and retained connected therewith by bearings which are not shown. The shaft may be moved vertically or endwise in said bearings and then rotatively by electro-magnetically- 105 operated ratchet and pawl mechanisms, the vertical or end-wise step-by-step movements occurring first. Among the functions of the shaft is that of a holder for the line-wipers 35 and 36 and the private-wiper 37. The 110 former two comprise a set distinct from the latter, but both sets are located within range of the contacts of their respective banks 32 and 33. Said wipers are not only insulated from the shaft, but from each other as well. Among the details that are associated with the shaft is a cam piece 38 which is of a split sleeve design and secured to the shaft by a screw 39. Said cam abuts on a hub 40 that is shrunk to the shaft near the middle of the 115 latter. This hub carries a set of longitudinal teeth 41 that serve, as will be disclosed, to enable the forward rotation of the shaft and as a locking means against backward rotation of the same. On the neck portion of 120

said hub there is found a set of circular teeth 42 that serve in turn as a means by which the raising of the shaft is accomplished and for locking it when raised. These circular teeth are traversed by a groove or channel 43 into which the end of a so-called shaft-rest 44 normally projects; but when the shaft is rotated any one of the said circular teeth which may be at the proper height slides onto the end of the said rest. The end of the rest is, of course, adapted to fit the said circular grooves between the ratchet-teeth. The upper surface of the rest is level, but the under side of the end thereof is chamfered to correspond with the upper slope of the circular teeth. Above the hub 40 the shaft carries an arm 45 known as the normal-post-arm and which is, while the switch-shaft is at rest, and while the shaft-rest occupies the slot 43, retained against the normal-post 46 by the coiled spring 47. Said normal-post-arm 45 is given control over a switch-shaft-spring 48, so that when the shaft is in normal position said spring is retained in connection with the contact-point 49, but when the shaft is raised said spring leaves the said contact-point 49 and engages instead with the contact-point 50. Among the magnets allotted to the first-selector some are used as relays and others as operating magnets. The magnets 51 and 52 are among the former kind and are known as the vertical and rotary line-relays. By means of their respective armatures 53 and 54 the springs 55 and 56 are controlled with respect to the ground-spring 57. Said springs are comprised in energizing circuits of operating magnets that raise and rotate the shaft. Another relay, known as the bridge-cut-off relay 58, controls through the medium of the armature 59 three springs 60, 61 and 62 that control the connection between the line-relays 51 and 52 and the non-grounded terminal of the central battery B. Also, the magnet 63 with an armature 64 that controls the springs 65 and 66 constitutes the back-release-relay which is used for restoring the switch after it has seized a trunk-line. Of the operating magnets the magnet 67 is known as the vertical-magnet and has a so-called vertical-armature 68 that is supported by pivots 69. Whenever the coils 70 and 71 of said vertical-magnet become energized the armature 68 is attracted, and when the magnetization ceases the retracting spring 72 restores said armature to its normal position. The upward movement of the armature is limited by the pole-pieces of the magnet-coils 70 and 71, and the lower limit is marked by a section of the switch-frame (not shown) that passes under the arm 73. Said arm is known as the vertical-arm and extends forwardly from the vertical-armature 68, of which latter it is a part. The vertical-arm carries on its end a so-

called vertical-pawl 74 which, when the vertical-armature is attracted, engages with some one of the circular teeth 42 to raise the shaft. Normally the under surface of the upper section of said pawl rests against a piece (not shown) that is secured to the switch-frame and that retains the pawl away from the circular teeth. When the vertical-armature is attracted, as the said pawl rises, a retracting-spring 75 thrusts the upper side of the pawl toward the circular teeth 42. As soon as said pawl clears or disengages its normal rest, and by the time that the vertical-armature strikes the pole-pieces, the vertical-pawl strikes with the rear surface of its upper section a bumper piece or stop which constitutes a part of the switch-frame. Therefore, the shaft is thus prevented from being thrown up more than one notch at a time by its own momentum. It is clear, then, that the said pawl not only raises the shaft, but that it also acts as a lock at the end of each stroke.

The vertical-arm also has an L-shaped piece 76 on its under edge that projects under a so-called release-link 77 of flexible spring material. Said link carries an aperture 78 on its front end, and is secured to the armature 79 of the operating magnet 80 known as the release-magnet. Said armature is suspended from the frame by the supports 81 and normally retained by the spring 82 away from the pole-piece of the release-magnet. A stop is suitably provided behind said armature to limit its movement when retracted. The first-selector is provided with a peculiarly shaped mechanism 83 known as the double-dog. It is pivoted so that it may swivel about a vertical axis that passes through the pivots 84. On its front side said double-dog develops into two dogs 85 and 86 which are so situated and constructed that the former may coöperate with the circular teeth 42, while the switch-shaft is raised and in normal rotary position, and the latter with the longitudinal teeth 41 when the shaft is rotated. To the right of the pivots 84 the body of the double-dog extends rearwardly, and projecting down therefrom is an arm 87 that comes into use very prominently during the releasing of the switch. Near the extremity of and on the upper side of said body a pin or lug 88 projects upwardly. Said lug is normally caught in the aperture 78 of the release-link 77, and because of the action of the spring 82 through said link the dogs 85 and 86 are retained away from the shaft. Always, at the first stroke of the vertical-armature, the link 77 is drawn from the lug 88 by the piece 76, and then the double-dog is rotated by the retracting-spring 89 so that the dog 85 falls under the first circular tooth, and so that when the vertical-armature returns to its normal position the said shaft is retained by said dog 130

in its new position. The release-link 77, while the double-dog is free, rests with its free end upon the lug 88 and out of locking engagement therewith. When the vertical-magnet 5 is energized a second time the shaft is raised a second step and the dog 85 at the second stroke passes from under the first tooth to below the second tooth, holding the shaft again as before. The release-magnet 80 is 10 composed of two coils like the vertical-magnet 67, but as a matter of convenience of illustration only one coil is shown. If while the shaft is raised the said release-magnet should be energized, the release armature 79, 15 of course, is attracted and the release-link 77 is thrust forward to catch the lug in the aperture 78. Upon the deenergization of the release-magnet the retracting-spring 82 then withdraws the dogs 85 and 86 from the shaft, 20 which latter being deprived of its only support then falls to normal position by its own weight. After the shaft is once raised it may be rotated by a second operating magnet 90 known as the rotary-magnet. Said 25 magnet has two coils 91 and 92 and unlike the vertical-magnet has its armature 93 pivoted in a vertical plane. Said armature may be moved about a vertical axis that passes through the pivots 94. The limit of 30 movement of said armature toward the rotary-magnet is determined by the pole-pieces of said magnet, which movement is produced by the rotary-magnet itself. The motion of the armature in the opposite direction is pro- 35 duced by the retracting-spring 95, and is limited by a switch-stop (not shown) behind the so-called rotary-arm 96. This arm, like the vertical-arm, carries a so-called rotary-pawl 97. Similar to the vertical-pawl, said 40 rotary-pawl normally rests against a stop (not shown) that retains it away from the longitudinal teeth, and when the rotary-armature is attracted it is drawn into engagement with the longitudinal teeth by a spring 98 that is attached between the rotary-arm and the rear of said pawl. By the 45 time that the rotary-armature strikes the pole-pieces of the rotary-magnet, the rotary-pawl also strikes a bumper-post, as does the vertical-pawl, and locks the shaft against 50 further advance by the force of its own momentum. At the end of the first rotary step the dog 86 falls behind the first longitudinal tooth, so that when the rotary-pawl falls 55 back the shaft is retained. It should be evident that as the shaft is rotated the vertical-dog 85 is extricated for a moment from the groove below the circular tooth with which it has been in engagement, by the 60 passage of the rotary-dog 86 across the longitudinal tooth over which it has to slide at the time; but at the beginning of the rotation it will be evident that the tooth which has been caught by the vertical-dog slides 65 onto the shaft-rest 44, and in this way the

shaft is still held raised after the rotation begins. The construction is such that when any one of the circular teeth passes onto its shaft-rest 44 the shaft rises a trifle in order that the tooth that has been resting upon the dog 85 may clear said dog and reduce the friction of the parts during operation. When the shaft is raised the circular tooth abutting on the shaft-support 44 is slightly below the level of the upper surface of the shaft-rest 44, and to enable a rotating tooth to pass onto the shaft-rest 44 the edge of the end thereof, as well as the edge of all circular teeth, are rounded off slightly to enable the rotary-armature 93 to raise the shaft 80 slightly, as stated, without catching.

The rotary-armature is provided with a so-called interrupter-finger 99 that separates the interrupter-springs 100 and 101 whenever the rotary-armature is attracted; also 85 with a rotary-armature-finger 102 that exercises certain controlling influences over the armature of the last of the operating magnets—the private-magnet 103. The said private-armature 104 works about a horizontal axis that passes through the supporting points 105. This armature is formed with a forwardly projecting arm 106, the latter having two flat surfaces in an approximately horizontal plane. Furthermore, the end of the said arm is bent downwardly at right angles and carries certain mechanical details, namely a lateral arm 107 which is designed to control circuits comprising the private-springs 108, 109 and 110, 100 and a tooth escapement which includes two flexible springs 111 and 112, each of which springs is riveted by one end to the arm 106, one on the upper side and the other on the lower. The upper spring is straight and has formed on its end two tooth projections 113 and 114 which extend downwardly, while the lower one is bent down and at right angles again to the front. This double angle on the lower spring is so designed that the latter may clear the bent portion of the private-arm, against which portion said spring rests with a requisite degree of tension, and so that there may be space in front of said bent portion to receive two other tooth-shaped upwardly projecting pieces 115 and 116 that are formed on the forward end of said escapement-spring 112, and which are sustained in juxtaposition to the upper teeth, but slightly to the rear thereof. A retracting-spring 117, suitably located, holds said armature normally away from the private-magnet pole-piece. A well-known auxiliary switching mechanism common to such switches is the 125 so-called side-switch. It is shown in connection with the first-selector A and comprises an arm 118 which is secured to the switch-frame in such a manner that it may be made to swing about a vertical axis that 130

passes through the pivots 119. The right extremity of said arm is drawn out into a finger 120 that works in conjunction with the escapement teeth previously described.

5 Said teeth, in a manner to be shown, convert the outward movement of the side-switch, by means of said finger, to a step-by-step motion, which movement is produced by a retracting-spring 121. At the base of 10 the finger 120 a lug 122 that is bent to the front is adapted to strike the cam 38 at a suitable time. Whenever the shaft is rotated, however, said cam is carried beyond the reach of said lug. Near its left extremity 15 the arm 118 carries a number of wipers 123, 124, 125 and 126 suitably mounted upon a pin 127 and insulated therefrom and from each other. Said wipers are known as the side-switch-wipers and are adapted to be operated 20 by the private-magnet and escapement device previously explained. If the private-magnet is energized once the private-armature is drawn down once and restored to its normal position. The escapement finger 120 then passes from behind the tooth 115 to the rear of the tooth 113 at the downward stroke of the private-armature 104, and from behind the latter tooth at the 25 return stroke. As soon as the escapement finger 30 clears or disengages the latter tooth the retracting-spring 121 draws the side-switch to the second position, where it is stopped by the lug 122 when it strikes the cam 38. Immediately, then, when the rotary-magnet energizes, the shaft is rotated 35 and the cam passes out of reach of the lug 122. Then the finger 120 of necessity falls against the tooth 116, because of the tension in the spring 121. The rotation of the shaft 40 results when the rotary-armature 93 is attracted by the rotary-magnet, and at the same time the rotary-armature-finger 102 depresses the private-armature 104 and causes the finger 120 to disengage from the 45 tooth 116 and advance against the tooth 114. Then, as the rotary-armature returns to normal position, when the rotary-magnet de-energizes, the private-armature on following the finger 102 permits the escapement-finger 50 120 to escape from the last tooth 114, thus permitting the side-switch to pass to the third position with the said finger resting against the side-switch-stop 128. In their normal positions the side-switch-wipers 123, 55 124, 125 and 126 engage with the contact-points 129, 130, 131 and 132, respectively. This position is known as the first position of the side-switch, at which time, it will be clear, the finger 120 is held behind the escapement tooth 115. In the second position, 60 while the said finger is between the teeth 116 and 115, the said side-switch-wipers engage instead with the contact-points 133, 134, 135 and 136, respectively; and when the said finger 65 120 falls against the stop 128 the wipers

shift their positions into contact with the contact-points 137, 138, 139 and 140, respectively.

Between the pivots 119 and the wiper supporting pin 127 a rearwardly-extending arm 141 on the side-switch-arm 118 pivotally supports on its end one end of a link 142, the other end of which latter, being bifurcated, engages with the lower end of the double-dog-arm 87 which is constructed somewhat in the shape of an inverted T. Should the release-magnet be energized while the side-switch is in third position, and, of course, while the shaft is rotated, the release-link 77, being attached to the release-armature 79, is then thrust forward 70 when the release-armature is attracted, and catches the lug 88 in the aperture 78. Then, when said release-armature is restored, the spring 82, as before described, withdraws 75 the dog 86 from the longitudinal teeth 41. At the same time the arm 87 drives the link 142 back, which latter then rotates the side-switch-arm about the pivots 119 against the tension of the side-switch retracting-spring 121, and thus drives the finger 120 80 backward between the springs 111 and 112 and into a position behind the tooth 115, locking the side switch in the first or normal position. The switch-shaft being unlocked 85 by the removal of the dog 86, and being thus left free, is then rotated by the coil spring 47 until the instant that the end of the shaft-rest enters the slot 43, at which time the shaft then drops to its normal position. Therefore, after the switch has been operated, the energization and deenergization 90 of the release-magnet is sufficient to restore the switch completely to its normal position. The line and private banks are each provided with ten rows of contact terminals, 95 each row consisting of ten sets of contacts, and the shaft is so constructed that it may be raised to any one of ten levels, and at each level it may be rotated ten successive 100 steps in order that the wipers which it carries may be placed in connection with any one of the ten sets of contact terminals in each level. All parts comprised in circuits 105 are properly insulated in order that they 110 may not come in contact with the switch-frame. For instance, the armatures 53, 54, 59 and 64 are tipped with insulating pieces 143, 144, 145 and 146, respectively, so that the springs which said armatures control 115 may not be grounded on the switch-frame. In like manner the wipers 35, 36 and 37 are 120 suitably insulated from the collars 147 that hold them, which collars are secured to the switch-shaft by means of suitable screws. 125

The connector C is of an improved automatic ringing common battery type, and may be modified if desired, but a standard type is represented in Fig. 3. The said connector C and the first-selector A are very 130

similar, but in the provision of relays and circuits the two switches are quite different. Like the first-selector A the said connector C is located above the line and private banks 148 and 149, respectively, with which the switch-shaft-wipers 150, 151 and 152 respectively engage. The said wipers, as in the first-selector, are mounted upon a switch-shaft 153, which shaft is provided, in addition, with the usual cam 154, longitudinal teeth 155, circular teeth 156, normal-post-arm 157, and coiled spring 158, the outer end of which latter is attached to the normal-post 159. The circular teeth 156 are traversed by the usual longitudinal slot 160 in which the shaft-rest 161 operates. The connector-switch like the first-selector has two line-relays, the vertical-line-relay 162 and the rotary-line-relay 163. These two relays between them and by means of their respective armatures 164 and 165 control the so-called line-relay-springs 166, 167 and 168 and the trunk-release-springs 169 and 170. The vertical-magnet 171, the release-magnet 172, the rotary-magnet 173 and the private-magnet 174 are severally similar to those described in connection with the first-selector and perform similar functions. The release-magnet, however, as distinguished from the release-magnet of the first-selector, has its armature 175 located on the right side instead of on the left. Said armature is provided with an elongated member 176 for controlling the double-dog 177 at the release. Said double-dog is a familiar element and the exercising control of the said release-armature 175 will be hereinafter described. The release-link 178 of the connector, unlike the release-link of the first-selector, is permanently fixed to a suitable part of the switch by the pin 179. Normally said release-link has a downward spring tendency or tension and acts as a latch for retaining the double-dog 177 normally disengaged from the switch-shaft 153, at which time the upwardly projecting pin 180 upon the upper side of the body of the double-dog 177 is retained within the aperture 181 provided upon the right extremity of said release-link 178. The L-shaped piece 182 upon the under side of the vertical-arm 183 reaches under said release-link, and whenever the switch is brought into use and at the first upward movement of the said vertical-arm 183 the said L-shaped piece, as in the first-selector, wrenches the release-link from engagement with the pin 180. While the switch is in operation the said release-link is disengaged from the said double-dog 177 and rests with its end upon the pin 180 and with the vertical and rotary dogs 184 and 185 in engagement with the shaft 153. The double-dog 177 is returned from its operative to its normal position by the release-armature 175

when the release-magnet 172 is energized. Upon the energization of said magnet the elongated portion 176 of the release-armature 175 strikes the double-dog 177 to the right of its bearings 186, so that the pin 180 is driven under the aperture 181 of the release-link 178 and caught therein. The rotary-magnet-armature 187 of the connector is somewhat more simple than that of the first-selector. It is provided with the rotary-arm 188 and with the rotary-pawl 189. The shaft being raised, each time that the rotary-magnet 173 is energized it rotates the switch-shaft one step at a time in the same mechanical manner that the first-selector-shaft is rotated by the first-selector rotary-arm each time the rotary-magnet is energized. The private-magnet 174 is designed to control, in a step-by-step manner, the operation of the side-switch from first to second and from second to third positions, by means of the escapement-teeth 190, 191, 192 and 193 and the escapement-finger 194, which operation results from the retracting tension of the side-switch retracting-spring 195. The private-magnet 174, furthermore, through the medium of the laterally projecting arm 196, controls four private-springs 197, 198, 199 and 200, so that when the said magnet 174 is energized the former two (197 and 198) of said springs that normally rest in engagement are separated and the springs 198, 199 and 200 that are normally out of contact are closed into contact—that is, when the private-armature is attracted the springs 197 and 198 will be found out of engagement and the springs 198, 199 and 200 in engagement. It will be understood that the connector switch-shaft 153 after being raised and rotated may be restored to normal position together with the side-switch (the latter, of course, being out of normal position) at the energization of the release-magnet 172. The release-magnet 172 being energized after the switch has been operated, the side-switch and double-dog are thrust into normal position by means of the double-dog release-arm 201 and the side-switch-link 202, and through the medium of the release-armature member 176, against the tension of the retracting-springs 195 and 203. At the same time, the shaft being deprived of its locking member (the rotary-dog 185) is rotated by the coiled spring 158 to normal rotary position, which shaft then as usual falls to normal vertical position.

The connector C also has a couple of auxiliary-relays 204 and 205 and a couple of differential-relays 206 and 207 for purposes to be disclosed hereinafter. The relay 204 controls by its armature 208 a couple of springs 209 and 210 that are normally in contact with the springs 211 and 212, and the relay 205 by its armature 213 controls a

spring 214 that normally engages the spring 215; and when the relay 205 is energized the armature forces the said spring 214 onto the spring 216 and the latter onto the spring 217; but it will be understood that the spring 215 follows up the spring 214 for a short distance, so that there comes a time when the springs 214, 215, and 216 are in contact for a moment. The differential-relay 206 is provided with two windings 218 and 219 which are connected with the vertical and rotary line-relays 162 and 163, respectively, which line-relays are in turn connected with the main trunk-conductors that 15 lead, as shown in Fig. 1, to the first-selector-banks 32 and 33. Whenever either or both of said trunk-conductors are grounded the said differential-relay 206 becomes energized, but when one is connected to ground and the 20 other to the non-grounded terminal of the central battery B said relay does not energize. The said differential-relay has under its control three springs 220, 221 and 222 of which the springs 220 and 221 are normally 25 in contact, but when the said relay is energized the spring 221 is forced away from the spring 220 and brought into engagement with the spring 222. Similarly, the differential-relay 207 is provided with two windings 30 223 and 224 which are connected with the vertical and rotary line-wipers 151 and 150, respectively. The said relay is so constructed that whenever either or both of the said line-wipers are connected to the ground terminal of the battery B the said relay does 35 40 45 50 55 60 65 70 75 80 85 90 95 100 105 110 115 120 125 130 not energize. In general, therefore, the windings of either of said differential-relays 206 and 207 if energized in a series circuit, do not energize the relay. The ringer-relay 225 is a feature common to all the connectors of the general type under consideration and has power when magnetized by means of its armature 226 to disconnect the terminals of the calling line from those of the called line, and to place across the latter the terminals of a ringer-generator 227. This operation is accomplished by means of the said armature 226, and the ringer-relay-spring 228, 229, 230, 231, 232 and 233. When said armature 226 is attracted the springs 229 and 232 that normally rest in contact with the springs 228 and 231, respectively, are separated from said springs and pressed into contact with the springs 230 and 233. At the central station and usually upon the shaft of the generator there is provided a circuit-interrupter 234 which when the connector C is operated for certain purposes causes the said ringer-relay to be intermittently energized and deenergized.

65 In Fig. 1 the first-selector A¹ that is asso-

ciated with the called line is identical with the first-selector A of the calling line and needs no further explanation, since like parts are likewise represented. When reference is made to the parts of said called first-selector it will be understood that their functions and constructions are the same as those already described for the first-selector A. In the particular system shown it will be clear that there may be a multiplicity of substations each of which is connected with the central station by a line of two conductors each of which lines has permanently allotted to it a first-selector. The first-selectors may be subdivided into groups of one hundred 70 75 80 85 90 95 100 105 110 115 120 125 130 each with all suitable line-bank-terminals of a given group connected in multiple, a similar arrangement being followed in connection with the private-bank-terminals. For each level of first-selector line-bank-terminals one set of ten trunk-lines is provided, with a connector connected to each one of said trunks. For each level to which a first-selector-shaft may be raised its line-wipers are placed on a level with a different set of 90 connectors for the purpose of reaching subscribers in different hundreds. Each first-selector is connected with a given set of bank-contact-points in the banks of the connectors of the given hundred to which said first-selector belongs, and when the first-selector comes into use a guarding potential is placed at the connector private-bank-contacts of the line of the calling first-selector to prevent any other calling subscriber from calling this same line. But while a line is idle a connection with said line is made over the trunk-conductors that extend between the connector-banks and the first-selector.

To more fully understand the operations and circuits in connection with my improved system a description will now be given of the circuits brought into use in the system when one subscriber calls another subscriber, for instance, as illustrated in Fig. 1 when the subscriber at substation #100 calls the subscriber at substation #220, which is as follows: The subscriber at the calling substation #100 removes his receiver from the switch-hook 2, and thus causes the ground-springs 20 and 21 to come into contact and to complete a circuit between the ground terminal G¹ and the ground-post 19, through the said springs 20 and 21 and the conductors 235 and 236. Immediately after, the vertical push-button 26 is pressed twice, then the rotary-button 27 once; again the first button 26 twice, and the second button 27 once, and for the last time the first button ten times, and the last button once. When the spring 30 is forced onto the ground-post 19 twice in succession for the first time, the vertical-line-conductor 237 is grounded twice, causing the vertical-line-relay 51 of the first-selector to become magnet-

ized and thereby momentarily attract its armature 53 twice. The energizing current that passes through said vertical-line-relay at this time enters the line at the ground terminal G¹, then passes to the ground-post 19 and through the spring 30 to the vertical-line-conductor 237, thence through the vertical-side-switch-wiper 125, contact-point 131, conductor 238, vertical-line-relay 51, bridge-cut-off-relay-springs 61 and 62 to the battery-lead 239 and to the non-grounded terminal of battery B to ground G. As a result the line-relay-spring 55 is forced onto the ground-spring 57 twice, which operation 5 closes a magnetizing circuit through the vertical-magnet 67. The current in this second circuit enters the line at the ground terminal G² and then passes through the springs 57 and 55 to the conductor 240 and through 10 the private-springs 109 and 108 and to the vertical-magnet 67, and to the battery-lead 239 to the non-grounded terminal of battery B and to ground G. The vertical-magnet 67 then attracts the vertical-armature twice 15 and raises the switch-shaft two steps. At the first step, of course, the release-link 77 is withdrawn from the double-dog 83, at which time the dog 85 engages with the circular teeth 42 and prevents the shaft from falling 20 to its original or normal position. As soon as the switch-shaft rises, the off-normal spring 48 then closes with the grounded contact-point 50, at which instant, and by which act, the connector private-bank-contacts that correspond to the line-conductors of the substation #100 are connected with ground, which connection establishes a guarding potential over said line, so that no subscriber may be able to connect with it 25 30 after once the first-selector A of said line has been operated. The vertical-line-conductor being grounded twice, then the push-button 27 in turn forces the spring 31 onto the ground-post 19 once and the rotary-line-conductor 241 is grounded once. An electric current then flows through the rotary-line-relay 52 for a moment, which magnetizes the said rotary-line-relay, causing the latter to attract its armature 54 once and force the 35 spring 56 against the ground-spring 57 once. As a result a magnetizing circuit is completed through the private-magnet 103. The electric current in this latter case flows from the ground terminal G² and thence through 40 the line-relay-springs 57 and 56 and conductors 242 and 243 to the private-magnet 103 to the battery-lead 239 and to the non-grounded terminal of battery B and to ground G. The private-armature 104 being 45 attracted once and restored immediately, the escapement-tooth 115 first clears the escapement-finger 120, which latter then falls against the second tooth 113; and when the armature returns to its normal position this 50 latter tooth also clears in turn the said 55

escapement-finger. At that instant the side-switch is drawn into the second position by the retracting-spring 121 with the cam-lug 122 resting against the cam 38.

It will be understood that the prongs of the bifurcated end of the link 142 that rests upon the T-shaped extremity of the double-dog releasing-arm 87 are of sufficient length to permit the said releasing-arm 87 to move from the position that it holds when the double-dog is held normally locked by the release-link 77 to the position it assumes when the said double-dog is released, without disengaging said prongs.

At the moment that the side-switch passes from the first to second position a circuit is completed through the rotary-magnet 90, when the side-switch-wiper 123 closes with the contact-point 133. The current then flows from the ground terminal G³ to the contact-point 133 and through the side-switch-wiper 123 and conductor 244 to the rotary-magnet-coil 92, thence through the interrupter-springs 100 and 101 and through the second rotary-magnet-coil 91 to the battery-lead and to the non-grounded terminal of battery B and to ground G. The rotary-magnet 90 then attracts the rotary-armature 93 and forces the rotary-pawl 97 into engagement with one of the longitudinal teeth 41, causing the shaft to rotate one step, since said shaft has already been raised. Just at the time, or at the instant before, the rotary-armature strikes the rotary-magnet pole-pieces, the rotary-dog 86 falls behind the first of the longitudinal teeth, in the manner already described, to prevent the shaft from returning to its normal position when the rotary-magnet becomes deenergized at the instant that the interrupter-finger forces the interrupter-springs apart and destroys the energizing circuit through the said magnet. This interruption occurs just at the time when the rotary-armature strikes the pole-pieces. At the same time that the rotary-pawl 97 advances to engage the longitudinal teeth, as described, the rotary-armature-finger comes into contact with the private armature 104, producing a depression of the latter at the same time that the rotary-pawl produces a rotation of the shaft. As the shaft begins to rotate the cam 38 very soon passes out of reach of the cam-lug and permits the escapement-finger 120 to fall against the tooth 116 before the rotary-armature-finger 102 has depressed the private-armature 104 too far. Very soon, however, the said tooth 116 is carried below the finger 120, which latter then falls against the upper tooth 114 at about the time that the shaft-wipers are rotated onto the first contact of the second level of their respective banks. As soon as the energizing circuit through the rotary-magnet is interrupted the rotary-armature then begins to 100 105 110 115 120 125 130 135 140 145 150 155 160 165 170 175 180

return to its normal position, and the private-armature 104 as well, following up the receding movement of the rotary-armature-finger 102. The tooth 114 clears the 5 escapement-finger 120 and the side-switch springs into third position with the escapement-finger against the side-switch-stop 128. The shifting of the side-switch takes place just before the interrupter-finger permits 10 the interrupter-springs 100 and 101 to re-engage, so that by the time they do re-engage the energizing circuit that has been described through the rotary-magnet has been destroyed between the side-switch-wiper 123 15 and the contact-point 133.

When the motion of the rotary-armature ceases permanently the operation of the first-selector comes to an end, the line-wipers 35 and 36 having seized upon an idle trunk-line similar to the trunk-line whose conductors 245 and 246 terminate at the tenth set 20 of contacts of the second level of the same line-bank. The seized line is protected from further seizure by a guarding potential at 25 the private-wiper and, therefore, at the first contact of the second level of the private-bank 33, and at all other private-contacts in multiple. Said guarding potential is established by reason of the connection between 30 the grounded terminal of battery B and said private-contacts, through the ground terminal G⁴, side-switch-wiper 124, conductor 247, back-release-relay 63, conductor 248 and the private-wiper 37. Similarly, should any 35 first-selector appropriate to its use the second trunk-line of the same level, a guarding potential will then appear at the second private-contact of the second level of the private-bank 33, as well as at all other 40 private-bank-contacts connected in multiple thereto. And should a third first-selector seize the third trunk-line on the same level a guarding potential will also appear at the third private-contact of the second level, and 45 should the fourth, fifth, etc., and ninth trunks be occupied guarding potentials would be found at the fourth, fifth, etc., as well as at the ninth private-contact-terminals of the second level of the private-bank. 50 Therefore, if the first nine trunk-lines of the second level are busy a guarding potential is found at each one of the first nine private-contacts of the second level of the private-bank 33. If this condition exists at the time 55 that the calling subscriber grounds his rotary-line-conductor by pressing button 27, the rotation of the shaft will not terminate as soon as the wipers have moved onto the first terminal of the level to which they have 60 been raised. The first nine private-contacts being grounded, then when the calling subscriber grounds the rotary side of the line the side-switch trips into second position in the manner described; but then the rotation 65 of the shaft will begin, not to cease until the wipers have been carried beyond the last of the busy trunk-lines—in this case onto the tenth terminal of the second level of the banks in question. This operation takes place in the following manner: The energizing 70 circuit through the rotary-magnet being closed, as was pointed out, at the juncture when the side-switch-wiper 123 engages with the contact-point 133, the rotary-armature is attracted by the rotary-magnet 90, and 75 the shaft is rotated one step in the manner described, so that the line and private wipers are rotated into engagement with the first terminal of the second level of their respective banks. At the same time the private- 80 armature is depressed by the rotary-armature-finger and the interrupter-springs 100 and 101 at the end of the stroke are separated by the interrupter-finger 99. There being a guarding potential at the first contact which 85 the private-wiper meets, a circuit is completed through the private-magnet 103 which extends from the grounded terminal of the battery B through the private-wiper of whatever first-selector is occupying the first 90 trunk of the second level in question, through the bank-multiplying-conductors to the contact-point with which the private-wiper 37 has engaged, thence through said private-wiper-conductor 248, winding of the back-release-relay 63, conductor 247, the side-switch-wiper 124, contact-point 134, conductors 249 and 243 and private-magnet 103 to the non-grounded terminal of battery B and 95 to ground G. The private-armature is thereby retained in the depressed condition, even after the energizing circuit is broken at the interrupter-springs, and while the rotary-armature-finger 102 returns to its normal position in response to the retracting tension 100 of the rotary-armature-spring 95. Since the escapement-finger 120 is held by the upper foremost escapement-tooth 114, and since the side-switch-wiper 123 is, therefore, retained in engagement with the grounded contact-point 133, as soon as the interrupter-springs 105 re-engage the energizing circuit through the rotary-magnet 90 is completed once more. As a result, the rotary-armature is attracted 110 again, the shaft is rotated one more step, and the private-wiper 37 is moved onto the second terminal of the second level of the private-bank 33. Said second contact also being grounded the energizing circuit through the private-magnet is still maintained 115 so that the side-switch is not liberated when the rotary-armature again returns to its normal position. Clearly, then, the shaft will be rotated in a step-by-step manner as long as the private-wiper continues to encounter grounded private-contacts. After 120 having rotated onto the ninth contact, the private-wiper is rotated one more step and into engagement with the tenth contact of the second level of the private-bank; but 125 130

this last contact is devoid of guarding potential, and as soon as the said wiper leaves the ninth contact the magnetizing circuit through the private-magnet that has up to 5 this time maintained the private-magnet energized is broken. This occurs at just about the time when the rotary-armature is at the end of its forward stroke, so that the private-armature that has up to this time 10 held the side-switch in its second position, by the magnetizing force that has now disappeared from the private-magnet falls back upon the rotary-armature-finger and follows said finger as the rotary-armature 15 returns to its normal position.

Between the time that the private-armature is released by the private-magnet and the time that the rotary-armature fully regains its normal position, the escapement-finger 120, which, during the rotation of the shaft, has been resting against the foremost tooth of the upper escapement-spring, disengages from said tooth and permits the side-switch to pass to the third position. 20 It is then that the side-switch-wiper 123 leaves the contact-point 133 and passes onto the contact-point 137. This disengagement occurs just before the interrupter-springs 100 and 101 reengage, so that the circuit 25 through the rotary-magnet is permanently broken in order that no further rotation of the shaft may take place during its operation. The side-switch-wipers 125 and 126 having engaged with the contact-points 139 30 and 140, the subscriber's line-conductors 237 and 241 are thereby extended through the respective side-switch-wipers 125 and 126 and over the conductors 250 and 251 to the vertical and rotary line-wipers 36 and 35, respectively. Said wipers are at the 35 time in engagement with the tenth contact of the second level of the line-bank 32 and place the calling subscriber #100 in connection with the connector C through the vertical and rotary trunk-conductors 245 and 246. The calling line #100 being thus extended, when the subscriber presses the vertical-button 26 twice for the second digit he again grounds the vertical-line-conductor 40 237 twice and thus operates the vertical-line-relay 162 of the connector C twice. The energizing current flows from ground G¹ to the ground-post 19, thence through the spring 30, conductor 237, side-switch-wiper 45 125 of the first-selector A, contact-point 139, conductor 250, vertical-line-wiper 36, vertical-trunk-conductor 245, vertical-line-relay 162 of the connector C, winding 218 of the differential relay 206 to the battery-lead 239 50 and to the non-grounded terminal of battery B and to ground G. The vertical-line-relay 162 of the connector C then attracts its armature 164 twice and the latter thereby forces the line-relay-spring 166 against the 55 ground-spring 167 twice. As a result, the

vertical-magnet 171 is energized twice in succession, raising the connector-shaft 153 one step each time by means of the vertical-armature 252 and the vertical-pawl 253. The current through the said vertical-magnet passes from ground G⁵ through the line-relay-springs 167 and 166, conductor 254, private-springs 197 and 198, conductor 255, side-switch-wiper 256, contact-point 257, conductor 258 to the said vertical-magnet 171 and thence to the battery-lead 239 and to the non-grounded terminal of battery B and to ground G. At the first movement of the vertical-arm 183 the release-link 178 is disengaged from the double-dog 177 by the L-shaped piece 182, and the vertical-pawl 253 then engages one of the circular teeth 156 and so raises the shaft 153 that the vertical-dog 184 catches and holds the said shaft in the raised position, in the manner described in connection with the first-selector A. At the second step of the vertical-armature 183 the shaft 153 is raised another step, in which new position it is retained by the said dog 184. The subscriber having thus raised the connector-shaft and placed the shaft-wipers 150, 151 and 152 opposite the first contact of the second level of the connector-banks, the next presses the rotary-button 27 once, grounding the rotary-line-conductor 241 as before, and causing thereby an energizing current to flow through the rotary-line-relay 163 of the connector C for a moment. This current flows from ground G¹ at the substation #100 to the ground-post 19, thence over the rotary-line-conductor 241 and through the first-selector side-switch-wiper 126, contact-point 140, conductor 251 to the rotary-line-wiper 35, thence over the rotary-trunk-conductor 246 and through the rotary-line-relay 163 and winding 219 of the differential-relay 206 to the conductor 259 and through the vertical-back-bridge-relay-springs 209 and 211 to the battery-lead 239 and to the non-grounded terminal of battery B and to ground G. The rotary-line-relay 163 being thus energized once has its armature 165 attracted once, which forces the springs 168 and 167 into contact. As a result the connector private-magnet 174 is energized by a current which flows from ground G⁵ through the springs 167 and 168, conductor 260, private-magnet 174, conductors 261 and 259, vertical-back-bridge-relay-springs 209 and 211 to the battery-lead 239 and to the non-grounded terminal of battery B and to ground G. The private-magnet 174 being energized for the first time the escapement-finger 194 110 clears the escapement-tooth 192 at the downward stroke of the private-armature 262, and clears the upper escapement-tooth 190 at the return stroke. 115

The side-switch, of course, is brought into second position and stopped when the lug 11.

- 263 strikes the cam 154; and the side-switch-wiper 256 having left the contact-point 257 is in engagement with the contact-point 264 instead, so that when the subscriber next 5 presses the vertical-button 26 ten times and energizes the vertical-line-relay 162 ten times the rotary-magnet 173 instead of the vertical-magnet 171 is magnetized ten times. The energizing circuit through the magnet 10 173 permits current to flow from ground G⁵ through the line-relay-springs 167 and 166, private-springs 197 and 198, conductor 255 and side-switch-wiper 256 to the contact-point 264 and rotary-magnet 173, thence to 15 the battery-lead 239 and to the non-grounded terminal of battery B and to ground G. The rotary-armature 187 is, therefore, attracted ten times—once each time that the rotary-magnet is energized. Each time that the said 20 armature is attracted, the rotary-pawl 189 engages one of the longitudinal teeth 155 and rotates the shaft 153 one step in the same manner that the first-selector-shaft is rotated. At the first circular step the shaft-rest 161 receives the shaft when the vertical-dog 184 is drawn out of engagement with the circular teeth 156 at the time that the rotary-dog 185 reaches the crest of the longitudinal tooth over which it has to pass at the 25 30 time; and by the time that the rotary-armature 187 strikes the rotary-magnet pole-pieces this last dog drops into locking engagement behind the said longitudinal tooth and retains the shaft in its advanced rotary position. At the first circular step the shaft-wipers 150, 151 and 152 pass onto the first contact of the second level of their respective banks 148 and 149, at the second step onto the second contact, and so on step by 35 40 step until they reach the tenth contact of the second level. The last step of the calling subscriber to complete his connection is to again ground the rotary-line-conductor 241 once by pressing the rotary button 27 once. 45 Again the rotary-line-relay 163 is energized and again the private-magnet 174 attracts its armature 262 once. The shaft having been rotated so that the cam 154 no longer obstructs the side-switch-arm 265, the escape- 50 55 ment-figure 194 at the downward stroke of the private-armature 262 clears the tooth 193, and when the said armature returns toward normal position the upper tooth 191 is also cleared, at which instant the said side-switch springs into third position. The passage of the side-switch to third position connects the private-wiper 152 with the ground terminal G⁶, when the side-switch-wiper 267 passes onto the contact-point 268. 60 65 This ground connection establishes a guarding potential at the tenth private-contact of the second level of the private-bank 149 that corresponds to the terminal of the normal-conductors 269 and 270 of the called subscriber, and at all other private-bank con- tact connected in multiple thereto, so that no other subscriber may call in upon said line while the said guarding potential exists.
- The calling first-selector, it will be remembered, places a guarding potential at the banks of the connectors of the hundred to which the subscriber #100 belongs, at the instant that the off-normal spring 48 comes into contact with the ground-spring 50, to prevent any subscriber from calling in upon the line of the calling subscriber. Therefore, neither the calling nor the called subscribers will be interrupted after they are once connected. The establishment of a guarding potential at the tenth contact of the second level of the private-bank 149 not only protects the called line from further seizure, but at the same time forces a current through the bridge-cut-off-relay 271 of the called first-selector A¹, which relay, by means of its armature, controls the bridge-cut-off-relay-springs 272, 273 and 274. The said relay, when magnetized, separates the said springs from each other and thereby 70 75 80 85 90 95 100 105 110 115 120 125 130 opens a bridge circuit normally established through the vertical and rotary line-relays 275 and 276, across the normal-conductors 269 and 270, and at the same time interrupts a connection between said relays and the non-grounded terminal of battery B, which terminal is directly connected with the spring 272. Since the said normal-conductors are included, one on each side of the main talking circuit, as hereinafter disclosed, it is desirable to remove said bridge from between them, for obvious and other reasons, to obtain the best results. The circuit through the said bridge-cut-off-relay 271 extends from ground G⁶ to the connector side-switch contact-point 268, side-switch-wiper 267, conductor 277, private-wiper 152, private-normal-conductor 278, spring 279, contact-point 280, bridge-cut-off-relay 271 to the battery-lead 239 and to the non-grounded terminal of battery B and to ground G. When the side-switch-wiper 267 passes onto the said grounded contact-point 268, still another circuit is established which comprises the ringer-relay 225 and the ringer-relay circuit-interrupter 234 in series. This last circuit extends from ground G⁶ to the contact-point 268, side-switch-wiper 267, conductor 281, rotary-back-bridge-relay-springs 215 and 214, vertical-back-bridge-relay-springs 212 and 210, conductor 282, ringer-relay 225, circuit-interrupter 234 to the battery-lead 239 and to the non-grounded terminal of battery B and to ground G. The said circuit-interrupter, it will be understood, is constructed somewhat like a commutator with alternate metallic and non-conducting segments in which the diametrically opposite metallic segments are connected directly together.

The brushes 283 and 284, furthermore, are arranged to touch the circumference of the circuit-interrupter at points 180 degrees apart and, therefore, the ringer-relay is energized each time the said brushes pass onto the connected metallic segments and is de-energized when they pass onto the insulation. Each time that the ringer-relay 225 is energized the ringer-relay-springs 229 and 232, as stated, are separated from the ringer-relay-springs 228 and 231 and forced onto the springs 230 and 233. These last two springs 230 and 233 constitute the terminals of the ringer-generator 227 which are thereby placed across the line-conductors 285 and 286 of the called subscriber #220. Each time that the ringer-relay circuit-interrupter 234 causes the said ringer-relay 225 to be energized a signaling impulse is sent out to the subscriber's line, which impulse occurring intermittently will ring the called subscriber's bell 287 intermittently until he answers or until the calling subscriber disconnects.

It will be noticed that each time that the vertical and rotary line-relays 162 and 163 have been energized the circuit comprises one of the windings of the differential-relay 206; but the energizing of said relay heretofore has played a part of no significance. Before going further it will be explained that if for any reason the called line is busy at the time that the calling subscriber #100 grounds his rotary-line-conductor 241 for the last time (to transfer the connector side-switch from second to third position) the guarding potential at the connector private-bank 149 will lock the side-switch in second position, to prevent it from passing to third position, and a busy signaling current is then sent to the calling subscriber to notify him that the connection with the called line has not been made. For instance, after the called line has been called by any connector there will be a guarding potential at the tenth private-contact of the second level of the private-bank 149, corresponding to the line of the called substation #220. Or, on the other hand, if the first-selector A¹ of the called line is in use the same private-bank-contact will be connected to ground for reasons described. The guarding potential, in this case, will reach the said contact-point by way of the private-normal-conductor 278.

At any rate if the private-wiper 152 finds a guarding potential at the said contact when the calling subscriber #100 grounds the rotary-line-conductor 241 for the last time the connector side-switch is locked in second position and prevented from passing to third position. The explanation of what occurs is as follows: The private-wiper 152 being connected to ground at the tenth contact of the second level, as stated, when the calling subscriber #100 grounds the rotary-

line-conductor by pressing the rotary-button 27 for the last time, the rotary-line-relay 163 is energized, as described, and as a result the private-magnet 174 is energized also. But when the rotary-line-relay 163 de-energizes the private-magnet 174 does not de-energize, because a local energizing circuit is provided elsewhere. The establishment of the said local energizing circuit for the private-magnet 174 is brought about in the following manner: When the private-magnet attracts its armature 262 the private-springs 198 and 199 are pressed into contact and, therefore, the rotary-back-bridge-relay 205 is energized. The energizing circuit for said rotary-back-bridge-relay may be traced as follows: From the grounded private-bank-contact in question through the private-wiper 152, conductors 277 and 281, rotary-back-bridge-relay-springs 215 and 214, rotary-back-bridge-relay 205 (Fig. 3), side-switch contact-point 289, side-switch-wiper 290, conductor 291, private-springs 199 and 198, conductor 255, side-switch-wiper 256, contact-point 264, rotary magnet 173 to the non-grounded terminal of battery B and to ground G. The rotary back-bridge relay 205 is thus energized through the rotary magnet 173, but since the resistance of said relay 205 is comparatively high as compared with that of the rotary magnet 173, the latter magnet is not energized, since the ampere turns are not sufficient to operatively energize said rotary magnet. At the instant the rotary back-bridge relay 205 attracts its armature 213, a holding circuit is provided for said relay independent of the grounded private bank contact, and at the same time a locking circuit is provided for the private magnet 174 to take the place of the original energizing circuit through the line relay spring 167 and 168, as described. The holding circuit for the relay 205 extends from ground G^o through the conductor 293, springs 216 and 214 and thence through the relay 205 and magnet 173 to battery. In order to insure the proper closing of the above circuit, the spring 214 is preferably adjusted so as to engage the spring 216 before it disengages the spring 215. The new holding circuit which is closed through the private magnet by the relay 205 extends from ground G^o through the conductor 293, rotary back-bridge relay springs 216 and 217, conductors 294 and 260, private magnet 174, conductor 261, vertical back-bridge relay springs 209 and 211 to the battery lead 239 and to the non-grounded terminal of battery B to ground G. The private magnet 174 will remain thus locked until the switches are released by the calling subscriber No. 100 and the escapement finger 194 is retained against the upper foremost escapement tooth 191. As long as the private armature 262 is depressed, a busy sig-

naling current is transmitted to the substation No. 100 of the calling subscriber, the circuit for which current is completed when the private spring 199 engages the spring 200. Just as the signaling of the called substation is dependent upon the automatic periodic energizing of the connector ringer relay 225, so is the busy signal that is transmitted to the calling sub-station #100. The energizing circuit for the said ringer-relay 225 for signaling, which was described, comprises the ground terminal G⁶ and the side-switch-wiper 267, but the energizing circuit during the busy signal, although it comprises first the grounded busy contact and finally the said ground G⁶, does not include the said side-switch-wiper 267, but branches off from the contact-point 268 to the conductor 293, and thence extends to the rotary-back-bridge-relay-springs 216 and 214, vertical-back-bridge-relay-springs 212 and 210 and conductor 282 to the said ringer-relay 225, thence through the interrupter 234 to the battery-lead 239.

The busy current, like the signaling current, is intermittent and is sent through the receiver 13 of the calling substation each time that the ringer-relay is energized. The busy current flows from the ringer-generator to the conductor 295, thence through the ringer-relay-springs 230 and 229, side-switch-wiper 296, contact-point 297, conductor 298, private-springs 200 and 199, conductor 291, side-switch-wiper 290, contact-point 289, condenser 299 to the trunk-conductor 246 and through the primary winding 7 to the vertical-trunk-conductor 245, and through the vertical-line-relay 162, winding 218 of the differential-relay 206 to the battery-lead 239, and to the non-grounded terminal of battery B, thence through the said battery to the ground terminal G and to the ground terminal G⁷ of the condenser 300, and back to the ringer-generator 227. Attention is called to the fact that a subscriber when calling a busy line may retain his line-wipers 151 and 150 across the normal-conductors 269 and 270 of the said line, but since the side-switch-wiper 267 is in second position, and since the rotary-back-bridge-relay 205 is energized and the spring 215 disconnected from all other springs, there is no guarding potential provided at the private-wiper 152 of the connector C under discussion. It will be evident then that the calling subscriber may leave his connector in the position described, after he receives the busy signal, without interfering in the least with other subscribers that may desire to call the line after the original guarding potential is in the meantime destroyed. That is, if subscriber X is connected with the subscriber #220 at the time that subscriber #100 calls and gets a busy signal, and the subscriber #100 does not restore his switches, the subscriber number X may disconnect from the subscriber #220 and another subscriber (number Y, for instance) if he desires, may call the subscriber #220 before the subscriber #100 releases. Attention is also called to the fact that during the busy lock-out the armature 262 of the private-magnet 174 disconnects the private-spring 197 (that is connected to the line-relay-spring 166) from the spring 198, so that no subsequent impulses that may be sent over the calling line will operate the connector C and cause its wipers 150 and 151 to pass onto any other contact. When the calling subscriber #100 hears the busy signal, and if he restores his receiver to the switch-hook 2, he will ground the vertical and rotary line-conductors 237 and 241 simultaneously by forcing the release-springs 22, 23 and 24 into contact. Therefore, the vertical and rotary line-relays 162 and 163 of the connector C will be energized simultaneously. The ground impulse to the vertical line, at the release, is sent from ground G¹ to the release-spring 22, thence through the springs 23 and 24 to the line-conductor 237, and thence through the vertical-line-relay 162 and winding 218 of the differential-relay 206 to the battery-lead 239 and to the non-grounded terminal of battery B. The ground impulse in the rotary-line-conductor 241 is sent from ground G¹, also to the said release-spring 22 and the spring 23, and to the rotary-line-conductor 241, thence through the rotary-line-relay 163, winding 219 of the differential-relay 206 and springs 209 and 211 of the vertical-back-bridge-relay 204 to the battery-lead 239, and to the non-grounded terminal of battery B and to ground G. The differential-relay is here energized at the same time that the trunk-release-springs 169 and 170 of the connector C are brought into contact, and as a result the release-magnet 172 of the connector is energized in series with the back-release-relay 63 of the first-selector. The current in this circuit is made to flow from the ground terminal G⁴ at the first-selector side-switch to the contact-point 138 and side-switch-wiper 124, thence through the back-release-relay 63 and private-wiper 37 to the trunk-release-conductor 301, to the connector trunk-release-springs 169 and 170, release-magnet 172 and differential-relay-springs 222 and 221 to the battery-lead 239, and to the non-grounded terminal of battery B and to ground G. As a result the connector-shaft 153 and side-switch are restored to normal position at the same time that the first-selector back-release-relay 63 is energized. When the connector-wipers leave their engaging bank-contacts the energizing circuit through the cut-off-relay 271 of the first-selector A¹ of the called line is destroyed. When this last energizing circuit 130

- is destroyed the first-selector A¹ of the called line is again free to operate in the usual manner. When the back-release-relay 63 of the first-selector A attracts its armature 64 after being energized, as described, the first-selector release-magnet 80 is energized also, which latter upon attracting its armature causes the release-link to latch the double-dog 83.
- 19 When the switch-hook 2 at the substation of the calling subscriber clears the release-springs the line-relays 162 and 163 of the connector C and the differential-relay 206 become deenergized, and as a result the 70 15 release-magnet 172 of the connector, together with the release-magnet 80 of the first-selector permit their armatures to regain their normal positions, at which time the first-selector-shaft 34 and side-switch 20 are restored also. But, as previously described, the calling subscriber by connecting with the called subscriber causes his signaling apparatus to be rung. The signaling current passes through the ringer 287 at the 80 25 called substation over the following circuit: from the ringer-generator 227 to the conductor 302, and through the ringer-relay-springs 233 and 232 to the side-switch-wiper 303, contact-point 304, conductor 305, winding 223 of the differential-relay 207, conductor 206, vertical - line - wiper 151, vertical - normal - conductor 269, vertical - line-conductor 285, condenser 307, ringer 287, ringer circuit springs 308 and 309, rotary - line - conductor 286, rotary - normal-conductor 270, rotary-line-wiper 150, conductor 310, winding 224 of the differential-relay 207, conductor 311, contact-point 312, side-switch-wiper 296 and ringer-relay- 90 30 35 springs 229 and 230 to the conductor 295 and back to the ringer-generator 227. The latter subscriber upon hearing the signal will remove his receiver 313 from the switch-hook 314. As soon as he does so an 40 energizing circuit is established through the transmitter 317 and primary winding 315 of the called substation, in series with the windings 223 and 224 of the differential-relay 207, and with the vertical and rotary 100 45 back-bridge-relays 204 and 205. The current in this circuit flows from the ground terminal G^o at the connector side-switch to the contact-point 268, side switch wiper 267, rotary-back-bridge-relay-springs 215 and 214 to the said rotary-back-bridge-relay 205, thence to the conductor 288, ringer-relay-springs 228 and 229, side-switch-wiper 296, contact-point 312, conductor 311, winding 224 of the differential-relay 207, subscribers #100 and #220 being thus connected and their transmitters 9 and 317 being thus energized in series with their respective primary windings 7 and 315, and 5 their respective receivers 13 and 313 being connected in series with the secondary windings 14 and 321, they may now communicate with each other in a well-known manner. The path of the voice-currents between the 10 two substations may be traced as follows: from the transmitter 9 of the calling substation #100 to the vertical-line-conductor 237 through the first-selector side-switch-wiper 125 and vertical-line-wiper 36, condenser 322, ringer-relay-springs 231 and 232, side-switch-wiper 303, winding 223 of the differential-relay 207, vertical-line-wiper 151, vertical-normal-conductor 269, vertical-line-conductor 285, transmitter 317, primary 15 winding 315, rotary-line-conductor 286, rotary-normal-conductor 270, and rotary-line-wiper 150, winding 224 of the differential-relay 207, side-switch-wiper 296, ringer-relay-springs 229 and 228, condenser 299, 20 rotary-trunk-conductor 246, rotary-line-wiper 35, side-switch-wiper 126, rotary-line-conductor 241 to the primary winding 7 of the induction-coil 8 and back to the transmitter 9.

25 30 The two subscribers having communicated, the subscriber at the called substation #220 (if the calling subscriber delays in releasing the connector from across his line) may release by hanging his receiver 313 upon the switch-hook 314. As the switch-hook descends the vertical and rotary line-conductors 285 and 286 will be grounded simultaneously for a moment, and as a result the rotary-back-bridge-relay 205 is de- 35 energized while the differential-relay 207 is energized. The deenergizing of the rotary-back-bridge-relay occurs because the said relay is short-circuited through ground. The short-circuit includes the ground terminal 40 G⁶ at the connector, side-switch contact-point 268, conductor 293, springs 216 and 214, coil 205, ringer-relay-springs 228 and 229, winding 224 of the differential-relay 207, rotary-line-wiper 150, rotary-normal- 45 conductor 270, rotary-line-conductor 286, release-springs 324 and 323 to ground G⁸. The winding 224 of the differential-relay 207 being thus short-circuited the current through said winding 224 is cut off and as a result the differential-relay is unbalanced 50 and becomes energized. The energizing circuit through the said differential-relay 207 is from ground G⁸, through the release-springs 323, 324 and 325 to the vertical-line- 55 conductor 285 and through the winding 223 of the said differential-relay 207 to the vertical-back-bridge-relay 204 and through the springs 220 and 221 of the differential-relay 206 to the battery-lead 239 to the non-grounded terminal of battery B and to 60 ground G. The deenergizing of the rotary-back-bridge-relay 205 is of little consequence, but the energization of the differential-relay 207 while the vertical and rotary line-relays 162 and 163 of the connector C 65 are energized results in releasing all of the switches. When the said differential-relay 207 attracts its armature the springs 326 and 327 are brought together and the connector release-magnet 172 is energized in 70 series with the first-selector back-release-relay 63 through a circuit in which current flows from the ground terminal G⁴ at the first-selector side-switch through the back-release-relay 63, thence through the connector trunk-release-springs 169 and 170 and release-magnet 172 and springs 327 and 326 to the battery-lead 239, and to the non-grounded terminal of battery B and to 75 ground G. As soon as the connector release-magnet 172 is energized the connector side-switch and switch-shaft 153 are restored and as a result the switch-shaft-wipers 150, 151 and 152 of the connector C are withdrawn from the tenth contact of the 80 second level of their respective banks 148 and 149, with the result that the bridge-cut-off-relay 271 is deenergized along with the differential-relay 207 and the vertical-back-bridge or pole-changing-relay 204. The 85 consequence is that the energizing circuit through the connector release-magnet 172 and first-selector back-release-relay 63 is destroyed and all parts of the connector as well as of the first-selector resume their 90 normal positions. Having thus disconnected the connector C from his own line the called subscriber #220 as a result has also restored his first-selector A¹ whereby he may, if he chooses, make a call. If, however, the calling subscriber is the one to restore his receiver first the vertical and rotary line-conductors 237 and 241 are grounded in the usual way and the primary result is that the rotary-line-relay 163 is deenergized and 95 the differential-relay 206 energized, since the winding 219 of the latter and the said rotary-line-relay 163 are short-circuited. Comprised in said short-circuit are the 100 ground terminal G⁶ at the connector side-switch, the rotary-back-bridge-relay-springs 216 and 214, the vertical-back-bridge-relay-springs 212 and 209, winding 219 of the differential-relay 206, rotary-line-relay 163, and rotary-line-conductor 241 and the 105 ground-terminal G¹ at the substation #100. Upon becoming deenergized the rotary-line-relay 163 permits the trunk-release-springs 170 and 169 of the connector C to be disengaged and at the same time the 110 differential-relay 206 forces the spring 221 from the spring 220 and into engagement with the spring 222. When the said spring 221 leaves the spring 220 the vertical-back-bridge-relay 204 is deenergized, which lat- 115 120 125 130

ter permits the springs 209 and 210 under its control to return to normal position. As a result the lead from the winding 219 of the differential-relay 206 is re-connected, when the springs 209 and 211 reengage, with the non-grounded terminal of battery B. As a result the rotary-line-relay 163 is reenergized and the differential-relay 206 strengthened by a flow of current from the 10 substation ground terminal G¹ through the said rotary-line-relay 163 and differential-relay-winding 219 to the battery-lead 239. At the instant that the trunk-release-springs 169 and 170 come into contact the connector 15 release-magnet 172 is energized in series with the first-selector back-release-relay 63 and the switches are restored as soon as the release-springs at the substation separate.

It will be evident that in a large exchange 20 where second-selectors are required, second-selectors of the trunk-release type may be employed. When a connection is established their position in a circuit is between the first-selector and the connector, and in this case 25 the third trunk-release-conductor 301 instead of terminating in the first-selector-banks terminates instead in second-selector-banks. Said second-selectors are almost identical with the first-selector, save that the 30 normal-conductors and the bridge-cut-off-relay are omitted. In addition the line-relays are provided with two trunk-release-springs similar to the trunk-release-springs 169 and 170 of the connector C. The back-release-relay is provided with two springs, one connected to one of said trunk-release-springs and the other to the other, whereby 35 energizing the back-bridge-relay will act the same as energizing both the line-relays. Furthermore, if the system is sufficiently 40 large to necessitate second-selectors between the first-selector A and the connector C, said second-selectors in such a position would find no use for the bridge-cut-off-relay and the normal-conductors that terminate 45 in the side-switch wipers 125 and 126. Also, it may be stated that if an exchange is very small it will not be necessary to employ selectors at all. In that case, the subscribers' 50 line-conductors would terminate directly in the connector line-relays—that is, the line-conductors 237 and 241 of Fig. 1 would be connected directly to the conductors 245 and 246, respectively, as shown in 55 Fig. 4. Another change that would be necessary for such a small exchange would be the direct connection of the trunk-release-spring 169 to the ground terminal G⁵, as shown in said figure. Upon the release, 60 both line-relays would be energized and the release-magnet 172 shown in Fig. 3 would be energized in a familiar manner.

I, therefore, provide an automatic common battery telephone system comprising 65 an automatic ringing connector in which

there are two differential-relays 206 and 207, one to act as a back-release-relay—that is, as a means whereby the called subscriber may disconnect any line from his own—and the other a front-release-relay, whereby 70 the calling subscriber, after the called subscriber has answered, and, therefore, after talking battery current has been supplied to both lines, may release the switches. I provide a connector in which the side-switch is 75 locked in second position when the connector calls upon a busy line, and which uses the ringer-generator as a busy signaling machine. I provide, furthermore, in said connector a private-magnet with an energizing 80 circuit controlled by the rotary-back-bridge-relay 205 and the said back-bridge-relay with a circuit controlled by the private-magnet and by the private-wiper of the connector, whereby when the private-magnet is 85 energized after the private-wiper is on a busy contact the said rotary-back-bridge-relay is energized and a new permanent circuit during the busy lock-out substituted for the other circuit of the private-magnet, and at 90 the same time a local and permanent circuit is established for the said rotary-back-bridge-relay, including springs under the control of said back-bridge-relay itself. I provide, also, an automatic energizing circuit 95 for the connector ringer-relay, comprising a couple of springs under the control of the vertical-back-bridge-relay, a couple of springs under the control of the rotary-back-bridge-relay, and one of the connector side-switch-wipers; said circuit being established 100 when the said side-switch-wiper, upon passing to third position, engages a grounded contact-point, and said circuit being interrupted by said back-bridge-relays whenever 105 they are energized. I provide a busy signaling circuit comprising a condenser connected from one terminal of the ringer-generator to ground and the central battery as well as other features of improvement 110 shown and described. These and other advantages and uses of my novel features and combinations will be obvious to those skilled in the art.

It will be understood, of course, that the 115 resistance of the different coils of the relays and magnets can be adjusted or varied to suit the requirements of different cases, with a view to obtaining the mode of operation described. For example, I have obtained good results by adjusting the resistance as follows: the rotary and vertical line-relays 162 and 163 one hundred ohms each; the windings 218 and 219 of the differential-relay 206 two hundred and fifty ohms each; the vertical-back-bridge-relay 204 three hundred and fifty ohms; the rotary-back-bridge-relay 205 three hundred and fifty ohms; the private-magnet 174 one hundred and seventy-five ohms; the release-magnet 130

- 172 sixty ohms; the vertical-magnet 171 sixty ohms; the rotary-magnet 173 sixty ohms; and the ringer-relay 225 five hundred ohms. The battery B can be of fifty volts.
- 5 During conversation, talking current is fed to the line of the subscribers through the coils of the line-relays and the back-bridge-relays of the connector, as well as through the differential-windings of the relay 206.
- 10 The said line-relays 162 and 163 and the said back-bridge-relays 204 and 205 are preferably of sufficient self-induction to enable them to act as impedance to prevent the passage of voice-currents through the battery.
- 15 Obviously, however, the windings of the differential-relay 207 must have as little self-induction as possible, in order to permit the passage therethrough of the voice-currents traversing the talking circuits.
- 20 With my improved arrangement, the calling subscriber merely calls the desired number, leaving the connector to do the ringing—that is, to apply the call-signal to the called line, thus making it unnecessary to 25 employ ringing-keys or push-buttons at the substations. Each connector is adapted to lock itself upon the called line, regardless of whether such line is busy or idle, until the calling subscriber hangs up his telephone,
- 30 or until the connection is released in some other manner. When a connector locks itself upon a busy line it does so in such manner as to preclude the calling subscriber from listening-in on the conversation
- 35 already being carried on over such line. At the same time, the connector automatically directs the current from the ringing-generator onto the calling line in such manner as to give the busy signal to the calling subscriber.
- 40 As explained, the locking of the connector on a busy line does not interfere with the use thereof by the subscriber or subscribers already in possession of such line. When a connector locks itself upon
- 45 a busy line, and if the calling subscriber should fail to hang up his receiver, the connector could stay thus locked without making the line busy (the subscriber's line with which it has attempted to make connection),
- 50 and without preventing the subscriber of this line from calling other subscribers and without preventing other subscribers from calling in on such line. The connector by its mechanism, and through the medium of
- 55 the ringing-generator, will automatically ring or call the called subscriber until the latter answers, or until the calling subscriber hangs up his telephone, providing, of course, that the called line was not found to be busy.
- 60 By "back-bridge-relays" I mean the relays, for example, which are in bridge at the right of the condensers 322 and 299. The line-relays 162 and 163 are front-bridge-relays. The expression "back-bridge" is
- 65 employed because the relays are in bridge at a point back of the said condensers relatively to the calling subscriber. The expression "front-bridge" is used because the relays of this bridge are located in front of the said condensers relatively to the calling subscriber. In other words, a bridge which is at the side of the condensers toward the calling subscriber is known as a front-bridge, while any bridge which is at the side of the condensers away from the calling subscriber is known as a back-bridge. It will be understood, of course, that condensers or any other suitable inductive connections can be employed for thus separating the front-bridge or bridges from the back-bridge or bridges.

- What I claim as my invention is:—
1. In a telephone system, a calling subscriber's line, a called subscriber's line, means whereby said called line is busy or occupied, and a connector for connecting the calling line with the called line, adapted to distinguish between busy and non-busy lines, provided with a ringer-relay, a busy-signal circuit for the calling subscriber's line, a busy-signal transmitter comprising a ringer-generator common to all subscribers, a circuit-interrupter common to all subscribers, and an energizing circuit for said ringer-relay, controlled by said circuit-interrupter, whereby each time the ringer-relay is energized current from the ringer-generator is sent through the busy-signal circuit to the calling subscriber's station.
  2. In a telephone system, a calling subscriber's line, a called subscriber's line, a common battery, and a connector for connecting the calling line with the called line, a ringer-generator common to all subscribers, adapted for providing all ringing or signaling current, having one terminal connected to ground, and a busy-signal circuit for the calling subscriber, comprising said ringer-generator and the said ground terminal and the common battery.
  3. In a telephone system, a calling subscriber's line, a called subscriber's line, means whereby the called line is already occupied or busy, and a connector for connecting the calling line with the called line, said connector adapted to distinguish between busy and non-busy lines, and provided with a three-position side-switch, a private-wiper, a busy-signal circuit for the calling subscriber's line, a ringer-generator common to all subscribers, a ringer-relay individual to the connector, and a circuit-interrupter for controlling the said ringer-relay, the said busy-signal circuit established when the connector attempts to connect the calling line with the called line, while the side-switch is in second position, closed each time that the said interrupter energizes the ringer-relay, and including said ringer-generator and contacts of said side-switch.

4. In a telephone system, a calling subscriber's line, a called subscriber's line, means whereby the called line is already occupied or busy, and a connector for connecting the calling line with the called line, said connector adapted to distinguish between busy and non-busy lines, and provided with a side-switch adapted to be locked in second position to establish a busy-signal circuit to 10 the calling subscriber's station.

5. In a telephone system, a calling subscriber's line, a called subscriber's line, means whereby the called line is already occupied or busy, and a connector for connecting the calling line with the called line, said connector provided with a side-switch and automatic means including a private-magnet for locking said side-switch in second position until the calling subscriber releases 20 the connector after failing to connect the two lines.

6. In a telephone system, a calling subscriber's line, a called subscriber's line, and a connector for connecting the calling line 25 with the called line, said connector including a side-switch, a private-magnet, a rotary-back-bridge-relay and a rotary-line-relay, the said private-magnet being controlled by the said rotary-line-relay, and circuits 30 for said private-magnet, one under the control of the said rotary-line-relay, and another under the control of the rotary-back-bridge-relay, the said rotary-back-bridge-relay being controlled by the said private-magnet, and also by said side-switch. 35

7. In a telephone system, a calling subscriber's line, a called subscriber's line, a connector for connecting the calling line with the called line, said connector including 40 condensers in the talking conductors thereof and provided with means including a differential-relay whereby the called subscriber may disconnect said connector from his line, and a trunk circuit including normally open contacts of said relay.

8. In a telephone system, a calling subscriber's line, a called subscriber's line, a contact allotted to the called line, and a connector for connecting the calling line with 50 the called line, said connector provided with means for distinguishing between busy and non-busy lines, a rotary-line-relay, a private-magnet, a rotary-magnet, a rotary-back-bridge-relay, energizing circuits for the 55 private-magnet, one controlled by the said rotary-line-relay and the other by the said rotary-back-bridge-relay, whereby when the rotary-line-relay is energized the private-magnet is energized and the latter in turn 60 causes the rotary-back-bridge-relay to be energized, said back-bridge-relay adapted to substitute one energizing circuit for the other, and an energizing circuit for the said rotary-back-bridge-relay, comprising the

said contact of the busy called line, contacts 65 controlled by the said relay itself, a number of springs controlled by the said private-magnet, and the winding of said rotary-magnet.

9. In a telephone system, a connector provided with a three-position side-switch and a private-magnet, together with a private-wiper and contacts and means whereby when the private-wiper finds a busy contact and if the private-magnet is energized the side-switch is then locked in second position. 70 75

10. In a telephone system, a connector provided with a side switch, said connector adapted to find a busy line and adapted to lock its side-switch in second 80 position when the wipers of said connector are set on said busy line, and also provided with means whereby if the said connector stays indefinitely upon said line any other subscriber may also call upon the same line, 85 if the original cause for making the said line busy is removed in the meantime, substantially as set forth.

11. In a telephone system, a connector provided with a rotary-line-relay, a private-magnet having a plurality of circuits, and a rotary-back-bridge-relay, one of the private-magnet circuits controlled by the rotary-line-relay, and the other controlled by the 90 rotary-back-bridge-relay. 95

12. In a telephone system, a connector having a private-magnet and a rotary-back-bridge-relay, a private-wiper, contact-points, and a plurality of circuits for said back-bridge-relay, one of which is controlled by 100 the private-magnet and established if the said private-magnet is energized while the private-wiper is on a busy contact-point.

13. In a telephone system, a connector having a rotary-line-relay and private-magnet, 105 a plurality of private-magnet circuits, a rotary-back-bridge-relay, a plurality of back-bridge-relay circuits, one of the private-magnet circuits controlled by the said rotary-line-relay, and another by the rotary- 110 back-bridge-relay, whenever the latter is energized, one of the energizing circuits of the said rotary-back-bridge-relay controlled by the said private-magnet, and a subscriber's rotary-line-conductor. 115

14. In a telephone system, a connector provided with a private-magnet and a side-switch and a rotary-magnet, and a rotary-back-bridge-relay provided with a plurality of circuits, one of said circuits controlled by 120 the private-magnet, comprising private-magnet springs, a plurality of side-switch-wipers, and the rotary-magnet.

15. In a telephone system, a calling subscriber's line, a busy called line, a connector, 125 a ringer-generator, and a busy-signal circuit for the calling subscriber's line, over which busy-signal circuit current is trans-

- mitted that originates in the ringer-generator.
16. In a telephone system, a calling subscriber's busy-signal circuit, a connector for establishing said busy-signal circuit when a busy line is called, a ringer-generator common to all subscribers, a circuit-interrupter common to all subscribers, a ringer-relay individual to the connector, controlled by said circuit-interrupter, and a busy-signal circuit for the calling subscriber for receiving current generated in the said common ringer-generator and transmitted over the said busy circuit each time that the said ringer-relay is energized after the connector is locked on a busy line.
17. In a telephone system, a busy-signal circuit for the calling subscriber's line, a ringer-generator, and a connector for establishing said busy-signal circuit, which circuit comprises a grounded condenser at the ringer-generator, a couple of ringer-relay-springs, a side-switch-wiper in second position, a couple of private-springs, a couple of side-switch-wipers, and a subscriber's station.
18. In a telephone system, a connector provided with a ringer-relay, means for applying ringing or calling signal current to a called subscriber's line when the ringer-relay is energized, an energizing circuit for said relay, said circuit provided with a plurality of switch-points all normally closed except one, and automatic means for closing said normally open switch-point when the connector seizes a called line.
19. In a telephone system, the combination of subscribers' lines, automatic means for applying ringing or call-signal current to any called line as soon as connection is established therewith if the same is not busy, and automatic means for diverting the said current to the calling subscriber to give a busy-signal if the called line is already in use.
20. In a telephone system, the combination of subscribers' lines, subscriber-controlled automatic switching machinery for establishing connection between calling and called lines, means for supplying ringing or call-signal current, automatic means for applying said current to a called line if the same is not busy, and automatic means for causing said current to be diverted over the calling line to give a busy-signal if the called line is already in use.
21. In a telephone system, the combination of subscribers' lines, subscriber-controlled automatic switching machinery for establishing connection between calling and called lines, means for supplying ringing or call-signal current, said switching machinery provided with electrically-operated automatic means for applying said cur-
- rent to a called line, and opening the talking circuit as soon as connection is established therewith, adapted to take the ringing current off and close the talking circuit when the called subscriber answers, and automatic means for intermittently interrupting the flow of ringing or call-signal current, adapted to produce an intermittent transmission of current to the called subscriber until the latter answers.
22. In a telephone system, the combination of subscribers' lines, a connector for establishing connection directly with the line of any called subscriber, and means for supplying ringing or call-signal current, said connector provided with electrically-operated automatic means for applying the said current to the called line and opening the talking circuit as soon as connection is established therewith, adapted to take the ringing current off and close the talking circuit when the called subscriber answers, and automatic means for intermittently interrupting the flow of ringing or call-signal current, adapted to cause an intermittent transmission of current to the called subscriber until the latter answers.
23. In a telephone system, the combination of subscribers' lines, automatic switching machinery for establishing connection between calling and called lines, a battery or centralized source of talking current controlled by said switching machinery, a centralized source of ringing or call-signal current, substation apparatus for said lines, said switching machinery provided with automatic means for applying the said ringing or call-signal current to a called line and opening the talking circuit as soon as connection is established therewith, and automatic means for taking off the ringing current and closing the talking circuit when the called subscriber answers.
24. In a telephone system, a connector provided with a talking circuit, condensers in said talking circuit, a differential-relay bridged across the circuit at one side of said condensers, and a differential-relay having its windings included in the talking circuit at the other side of said condensers, together with suitable circuits controlled by said relays.
25. In a telephone system, a connector provided with a pair of differential-relays, release mechanism, and a trunk release-circuit including contacts of said relays whereby either relay can close said trunk circuit.
26. In a telephone system, a connector provided with release mechanism, a trunk-release-circuit, normally open parallel branches in said circuit, and a pair of release-relays, each relay adapted to completely control one of said parallel branches.
27. In a telephone system, a connector

provided with release mechanism, a trunk-release-circuit, normally open parallel branches in said circuit, and a pair of differential-release-relays, each relay adapted to 5 control one of said parallel branches.

28. In a telephone system, a connector provided with a talking circuit, release mechanism, a release-circuit, a differential-relay controlling said release-circuit, said 10 relay having its windings serially included in said talking circuit, and condensers in said talking circuit.

29. In a telephone system, the combination of subscribers' lines, a connector, and 15 subscribers' devices for controlling said connector, the said connector provided with a private-magnet and a pole-changing-relay each controlled by the other, a battery, and circuits to be switched by the pole-changing- 20 relay from one pole of the battery to the other, substantially as set forth.

30. In a telephone system, a connector provided with a side-switch, a private-magnet for operating said side-switch, a pole- 25 changing-relay, said magnet and relay controlling each other, a battery, and circuits to be switched by the pole-changing-relay from one pole of said battery to the other.

31. In a telephone system, a connector 30 provided with a pair of differential-relays, a release-circuit adapted to be closed by the energization of either relay, a private-magnet and a pole-changing-relay each controlled by the other, a battery, and circuits 35 to be switched by the pole-changing-relay from one pole of said battery to the other.

32. In a telephone system, the combination of a pair of line-conductors, a battery having one pole normally connected with 40 both of said conductors, a private-magnet and a pole-changing-relay each controlled by the other, and means whereby the energization of the pole-changing-relay switches one line-conductor into connection with the 45 other pole of the battery.

33. In a telephone system, a call-signal apparatus comprising a ringer-relay, a local circuit for said relay, a pair of relays jointly controlling said circuit, and a line- 50 circuit for energizing said pair of relays, together with means by which a called subscriber closes said line-circuit to cause the deenergization of said ringer-relay.

34. In a telephone system, the combination of a calling line, a called line, a ringer-generator, a call-signal circuit including the called line and the ringer-generator, and a busy-signal circuit including the said generator and the calling line.

35. In a telephone system, the combination of a calling line, a called line, a ringer-generator, a condenser connecting one pole of the generator with the ground, a call-signal circuit including the called line and the gen-

erator, and a busy-signal circuit including 65 the condenser and generator and the calling line.

36. In a telephone system, a talking circuit, and a connector provided with two differential-relays, one a front-bridge-relay, 70 and the other back-relay, both relays de-energized during use of the circuit for talking purposes and both windings of each relay normally connected with the talking circuit.

75 37. In a telephone system, the combination of a common battery, a common battery connector including condensers in the talking conductors thereof, a back differential-relay, and a trunk release-circuit controlled 80 by the contacts of said relay.

38. In a telephone system, a connector provided with a release-magnet, release mechanism operated thereby, a plurality of energizing circuits therefor, a trunk conductor common to both circuits, a differential-relay controlling one of said circuits, and another differential-relay controlling the other circuit.

90 39. In a telephone system, the combination of a calling and a called line, means for establishing a connection between said lines, means for supplying ringing current to said called line, a ringer-relay for applying the current to said line, an energizing circuit for 95 said relay, means for supplying current to said circuit, said means operated independent of the calling line after the connection is established, and an interrupter for intermittently interrupting the flow of current 100 in said circuit, substantially as and for the purpose set forth.

40. In a telephone system, a connector adapted for establishing connection directly with the called subscriber's line provided 105 with a three-position side switch, and automatic means for locking the side-switch in second position if the called line is busy.

41. The combination, in an automatic telephone trunking system, of a calling 110 scribe's line, a called subscriber's line, and a connector for connecting the calling line with the called line, said connector being provided with private and rotary and vertical magnets, energizing circuits for said vertical and rotary magnets, controlled by and adapted to be opened by the energizing of the private-magnet, whereby when the private-magnet is energized it is impossible to 115 energize either of said vertical or rotary magnets, means for maintaining said private magnet energized after a busy line is found, trunk-lines, and automatic trunk-selecting switches each provided with means

120 for distinguishing between busy and idle trunk-lines, adapted to pass busy trunk-lines and stop on the first idle trunk-line.

42. The combination, in an automatic tele-

- phone trunking system, of a calling subscriber's line, a called subscriber's line, means whereby said called line is busy or occupied, and a connector for connecting the calling line with the called line, adapted to distinguish between busy and non-busy lines, provided with a ringer-relay, a busy-signal circuit for the calling subscriber's line, a busy-signal transmitter comprising a ringer-generator common to all subscribers, a circuit-interrupter common to all subscribers, an energizing circuit for said ringer-relay, controlled by said circuit-interrupter, whereby each time the ringer-relay is energized current from the ringer-generator is sent through the busy-signal circuit to the calling subscriber's station, trunk-lines, and automatic trunk-selecting switches each provided with means for distinguishing between busy and idle trunk-lines, adapted to pass busy trunk-lines and stop on the first idle trunk-line.
43. The combination, in an automatic telephone trunking system, of a calling subscriber's line, a called subscriber's line, a common battery, and a connector for connecting the calling line with the called line, a ringer-generator common to all subscribers, adapted for providing all ringing or signaling current, having one terminal connected to ground, a busy-signal circuit for the calling subscriber, comprising said ringer-generator and the said ground terminal and the common battery, trunk-lines, and automatic trunk-selecting switches each provided with means for distinguishing between busy and idle trunk-lines, adapted to pass busy trunk-lines and stop on the first idle trunk-line.
44. The combination, in an automatic telephone trunking system, of a calling subscriber's line, a called subscriber's line, means whereby the called line is already occupied or busy, and a connector for connecting the calling line with the called line, said connector adapted to distinguish between busy and non-busy lines, and provided with a three-position side-switch, a private-wiper, a busy-signal circuit for the calling subscriber's line, a ringer-generator common to all subscribers, a ringer-relay individual to the connector, a circuit-interrupter for controlling the said ringer-relay, the said busy-signal circuit established when the connector attempts to connect the calling line with the called line, while the side-switch is in second position, closed each time that the said interrupter energizes the ringer-relay, and including said ringer-generator and contacts of said side-switch, trunk-lines, and automatic trunk-selecting switches each provided with means for distinguishing between busy and idle trunk-lines, adapted to pass busy trunk-lines and stop on the first idle trunk-line.
45. The combination, in an automatic telephone trunking system, of a calling subscriber's line, a called subscriber's line, means whereby the called line is already occupied or busy, a connector for connecting the calling line with the called line, said connector adapted to distinguish between busy and non-busy lines, and provided with a side-switch adapted to be locked in second position to establish a busy-signal circuit to the calling subscriber's station, trunk-lines, and automatic trunk-selecting switches each provided with means for distinguishing between busy and idle trunk-lines, adapted to pass busy trunk-lines and stop on the first idle trunk-line.
46. The combination, in an automatic telephone trunking system, of a calling subscriber's line, a called subscriber's line, means whereby the called line is already occupied or busy, a connector for connecting the calling line with the called line, said connector provided with a side-switch and automatic means including a private-magnet for locking said side-switch in second position until the calling subscriber releases the connector after failing to connect the two lines, trunk-lines, and automatic trunk-selecting switches each provided with means for distinguishing between busy and idle trunk-lines, adapted to pass busy trunk-lines and stop on the first idle trunk-line.
47. The combination, in an automatic telephone trunking system, of a calling subscriber's line, a called subscriber's line, and a connector for connecting the calling line with the called line, said connector comprising a side-switch, a private-magnet, a rotary-back-bridge-relay and a rotary-line-relay, the said private-magnet being controlled by the said rotary-line-relay, and circuits for said private-magnet, one under the control of the said rotary-line-relay, and another under the control of the rotary-back-bridge-relay, the said rotary-back-bridge-relay being controlled by the said private-magnet, and also by said side-switch, trunk-lines, and automatic trunk-selecting switches each provided with means for distinguishing between busy and idle trunk-lines, adapted to pass busy trunk-lines and stop on the first idle trunk-line.
48. The combination, in an automatic telephone trunking system, of a calling subscriber's line, a called subscriber's line, a connector for connecting the calling line with the called line, said connector including condensers in the talking conductors thereof and provided with means including a differential-relay whereby the called subscriber may disconnect said connector from his line, trunk-lines, and automatic trunk-selecting switches each provided with means for distinguishing between busy and idle trunk-lines, adapted to pass busy trunk-lines and stop on the first idle trunk-line.

lines and stop on the first idle trunk-line, each selecting switch having a trunk-release circuit controlled by said differential relay.

49. The combination, in an automatic telephone trunking system, of a calling subscriber's line, a called subscriber's line, a contact allotted to the called line, and a connector for connecting the calling line with the called line, said connector provided with 5 means for distinguishing between busy and non-busy lines, a rotary-line-relay, a private-magnet, a rotary-magnet, a rotary-back-bridge-relay, energizing circuits for the private-magnet, one controlled by the said rotary-line-relay and the other by the said rotary-back-bridge-relay, whereby when the rotary-line-relay is energized the private-magnet is energized and the latter in turn causes the rotary-back-bridge-relay to be 10 energized, said back-bridge-relay adapted to substitute one energizing circuit for the other, and an energizing circuit for the said rotary-back-bridge-relay, comprising the 15 said contact of the busy called line, contacts controlled by the said relay itself, a number of springs controlled by the said private-magnet, and the winding of said rotary-magnet, trunk-lines, and automatic trunk-selecting switches each provided with means 20 for distinguishing between busy and idle trunk-lines, adapted to pass busy trunk-lines and stop on the first idle trunk-line.

50. The combination, in an automatic telephone trunking system, of a connector 35 provided with a three-position side-switch and a private-magnet, together with a private-wiper and contacts and means whereby when the private-wiper finds a busy contact and if the private-magnet is energized the 40 side-switch is then locked in second position, trunk-lines, and automatic trunk-selecting switches each provided with means for distinguishing between busy and idle trunk-lines, adapted to pass busy trunk-lines and stop on the first idle trunk-line.

51. The combination, in an automatic telephone trunking system, of a connector adapted to find a busy line and adapted to 45 lock its side-switch in second position when the wipers of said connector are set on said busy line and provided with means whereby if the said connector stays indefinitely upon said line any other subscriber may also call upon the same line if the original cause for 50 making the said line busy is removed in the meantime, trunk-lines, and automatic trunk-selecting switches each provided with means for distinguishing between busy and idle trunk-lines, adapted to pass busy trunk-lines and stop on the first idle trunk-line, substantially as set forth.

52. The combination, in an automatic telephone trunking system, of a connector provided with a rotary-line-relay, a private-magnet having a plurality of circuits, a ro- 55

tary-back-bridge-relay, one of the private-magnet circuits controlled by the rotary-line-relay, and the other controlled by the rotary-back-bridge-relay, trunk-lines, and automatic trunk-selecting switches each provided with means for distinguishing between busy and idle trunk-lines, adapted to pass busy trunk-lines and stop on the first idle trunk-line. 70

53. The combination, in an automatic telephone trunking system, of a connector having a private-magnet and a rotary-back-bridge-relay, a private-wiper, contact-points, a plurality of circuits for said back-bridge-relay, one of which is controlled by the private-magnet and established if the said private-magnet is energized while the private-wiper is on a busy contact-point, trunk-lines, and automatic trunk-selecting switches each provided with means for distinguishing between busy and idle trunk-lines, adapted to pass busy trunk-lines and stop on the first idle trunk-line. 75 80 85

54. The combination, in an automatic telephone trunking system, of a connector having a rotary-line-relay and private-magnet, a plurality of private-magnet circuits, a rotary-back-bridge-relay, a plurality of back-bridge-relay circuits, one of the private-magnet circuits controlled by the said 90 rotary-line-relay, and another by the rotary-back-bridge-relay, whenever the latter is energized, one of the energizing circuits of the said rotary-back-bridge-relay controlled by the said private-magnet, a subscriber's rotary-line-conductor, trunk-lines, and automatic trunk-selecting switches each provided with means for distinguishing between busy and idle trunk-lines, adapted to pass busy trunk-lines and stop on the first 95 100 105 idle trunk-line.

55. The combination, in an automatic telephone trunking system, of a connector provided with a private-magnet and a side-switch and a rotary-magnet, a rotary-back-bridge-relay provided with a plurality of 110 circuits, one of said circuits controlled by the private-magnet, comprising private-magnet springs, a plurality of side-switch-wipers, and the rotary-magnet, trunk-lines, 115 and automatic trunk-selecting switches each provided with means for distinguishing between busy and idle trunk-lines, adapted to pass busy trunk-lines and stop on the first idle trunk-line. 120

56. The combination, in an automatic telephone trunking system, of a calling subscriber's line, a busy called line, a connector, a ringer-generator, a busy-signal circuit for the calling subscriber's line, over which 125 busy-signal circuit current is transmitted that originates in the ringer-generator, trunk-lines, and automatic trunk-selecting switches each provided with means for distinguishing between busy and idle trunk- 130

lines, adapted to pass busy trunk-lines and stop on the first idle trunk-line.

57. The combination, in an automatic telephone trunking system, of a calling subscriber's busy-signal circuit, a connector for establishing said busy-signal circuit when a busy line is called, a ringer-generator common to all subscribers, a circuit-interrupter common to all subscribers, a ringer-relay individual to the connector, controlled by said circuit-interrupter, a busy-signal circuit for the calling subscriber for receiving current generated in the said common ringer-generator and transmitted over the said busy circuit each time that the said ringer-relay is energized after the connector is locked on a busy line, trunk-lines, and automatic trunk-selecting switches each provided with means for distinguishing between busy and idle trunk-lines, adapted to pass busy trunk-lines and stop on the first idle trunk-line.

58. The combination, in an automatic telephone trunking system, of a busy-signal circuit for the calling subscriber's line, a ringer-generator, a connector for establishing said busy-signal circuit, which circuit comprises a grounded condenser at the ringer-generator, a couple of ringer-relay springs, a side-switch-wiper in second position, a couple of private-springs, a couple of side switch-wipers, and a subscriber's station, trunk-lines, and automatic trunk-selecting switches each provided with means for distinguishing between busy and idle trunk-lines, adapted to pass busy trunk-lines and stop on the first idle trunk-line.

59. The combination, in an automatic telephone trunking system, of a connector provided with a ringer-relay, means for applying ringing or call-signal current to a called subscriber's line when the ringer-relay is energized, an energizing circuit for said relay, said circuit provided with three switch-points all normally closed except one, automatic means for closing said normally open switch-point when the connector seizes a called line, means for then opening the other two switch-points, trunk-lines, and automatic trunk-selecting switches each provided with means for distinguishing between busy and idle trunk-lines, adapted to pass busy trunk-lines and stop on the first idle trunk-line.

60. The combination, in an automatic telephone trunking system, of a connector, a plurality of subscribers' lines terminating in said connector, a calling mechanism for each subscriber's line, said mechanism operative by manual operation thereof to transmit current for one digit and then come to rest before receiving further manual operation for the next digit, means for supplying ringing or call-signal current to any called line, automatic means for applying

the ringing or call-signal current to the called line as soon as connection is established therewith, trunk-lines, automatic trunk-selecting switches each provided with means for distinguishing between busy and idle trunk-lines, adapted to pass busy trunk-lines and stop on the first idle trunk-line, and automatic means for taking off the ringing current when the called subscriber answers.

61. The combination, in an automatic telephone trunking system, of subscribers' lines, automatic means for applying ringing or call-signal current to any called line as soon as connection is established therewith if the same is not busy, automatic means for diverting the said current to the called subscriber to give a busy-signal if the called line is already in use, trunk-lines, and automatic trunk-selecting switches each provided with means for distinguishing between busy and idle trunk-lines, adapted to pass busy trunk-lines and stop on the first idle trunk-line.

62. In a telephone system comprising subscribers' lines and subscriber-controlled automatic switching machinery for establishing connection between calling and called lines, the combination of means for supplying ringing or call-signal current, automatic means for applying said current to a called line if the same is not busy, automatic means for causing said current to be diverted over the calling line to give a busy-signal if the called line is already in use, a plurality of trunk-lines, and automatic trunk-selecting switches each provided with means for distinguishing between busy and idle trunk-lines, adapted to pass busy trunk-lines and stop on the first idle trunk-line.

63. In a telephone system comprising subscribers' lines and subscriber-controlled automatic switching machinery for establishing connection between calling and called lines, the combination of a calling mechanism for each subscriber's line, said mechanism operative by manual operation thereof to transmit current for one digit and then come to rest before receiving further manual operation for the next digit, means for supplying ringing or call-signal current, said switching machinery provided with electrically-operated automatic means for applying said current to a called line as soon as connection is established therewith, automatic means for intermittently interrupting the flow of ringing or call-signal current, adapted to produce an intermittent transmission of current to the called subscriber until the latter answers, a plurality of trunk-lines, automatic trunk-selecting switches each provided with means for distinguishing between busy and idle trunk-lines, adapted to pass busy trunk-lines and

stop on the first idle trunk-line, and means for automatically removing the ringing current when the called subscriber answers.

64. The combination, in an automatic telephone trunking system, of subscribers' lines, a calling mechanism for each subscriber's line, said mechanism operative by manual operation thereof to transmit current for one digit and then come to rest before receiving further manual operation for the next digit, a connector for establishing connection directly with the line of any called subscriber, and means for supplying ringing or call-signal current, said connector provided with automatic means for applying the said current to the called line as soon as connection is established therewith, automatic means for intermittently interrupting the flow of ringing or call-signal current, adapted to cause an intermittent transmission of current to the called subscriber until the latter answers, trunk-lines, automatic trunk-selecting switches each provided with means for distinguishing between busy and idle trunk-lines, adapted to pass busy trunk-lines and stop on the first idle trunk-line, and means for automatically removing the ringing current when the called subscriber answers.
65. In a telephone system comprising subscribers' lines and automatic switching machinery for establishing connection between calling and called lines, the combination of a calling mechanism for each subscriber's line, said mechanism operative by manual operation thereof to transmit current for one digit and then come to rest before receiving further manual operation for the next digit, a common battery or centralized source of talking current, a centralized source of ringing or call-signal current, substation apparatus for said lines, said switching machinery provided with automatic means for applying the said ringing or call-signal current to a called line as soon as connection is established therewith, a plurality of trunk-lines, automatic trunk-selecting switches each provided with means for distinguishing between busy and idle trunk-lines, adapted to pass busy trunk-lines and stop on the first idle trunk-line, and means for removing said ringing current when the called subscriber answers.
66. The combination, in an automatic telephone trunking system, of a connector provided with a talking circuit, condensers in said talking circuit, a differential-relay bridged across the circuit at one side of said condensers, a differential-relay having its windings included in the talking circuit at the other side of said condensers, together with suitable circuits controlled by said relays, trunk-lines and automatic trunk-selecting switches each provided with means for

distinguishing between busy and idle trunk-lines, adapted to pass busy trunk-lines and stop on the first idle trunk-line.

67. The combination, in an automatic telephone trunking system, of a connector provided with a pair of differential-relays, release mechanism, a release-circuit, means whereby either relay can close said circuit, trunk-lines, and automatic trunk-selecting switches each provided with means for distinguishing between busy and idle trunk-lines, adapted to pass busy trunk-lines and stop on the first idle trunk-line, each selecting switch including said trunk release circuit controlled by said differential relays.

68. The combination, in an automatic telephone trunking system, of a connector provided with release mechanism, a release-circuit, normally open parallel branches in said circuit, a pair of release-relays, each relay adapted to control one of said parallel branches, trunk-lines, and automatic trunk-selecting switches each provided with means for distinguishing between busy and idle trunk-lines, adapted to pass busy trunk-lines and stop on the first idle trunk-line, each selecting switch having release mechanism controlled over said release circuit.

69. The combination, in an automatic telephone trunking system, of a connector provided with release mechanism, a release-circuit, normally open parallel branches in said circuit, a pair of differential-release-relays, each relay adapted to control one of said parallel branches, trunk-lines, and automatic trunk-selecting switches each provided with means for distinguishing between busy and idle trunk-lines, adapted to pass busy trunk-lines and stop on the first idle trunk-line, each selecting switch having release mechanism controlled over said release circuit.

70. The combination, in an automatic selecting telephone trunking system, of a connector provided with a talking circuit, release mechanism, a release-circuit, a differential-relay controlling said release-circuit, said relay having its windings included in said talking circuit, condensers in said talking circuit, trunk-lines, and automatic trunk-selecting switches each provided with means for distinguishing between busy and idle trunk-lines, adapted to pass busy trunk-lines and stop on the first idle trunk-line.

71. The combination, in an automatic telephone trunking system, of subscribers' lines, a connector, and subscribers' devices for controlling said connector, the said connector provided with a private-magnet and a pole-changing-relay each controlled by the other, a battery, circuits to be switched by the pole-changing-relay from one pole of the battery to the other, trunk-lines, and automatic trunk-selecting switches each pro-

vided with means for distinguishing between busy and idle trunk-lines, adapted to pass busy trunk-lines and stop on the first idle trunk-line, substantially as set forth.

72. The combination, in an automatic telephone trunking system, of a connector provided with a side-switch, a private-magnet for operating said side-switch, a pole-changing-relay-magnet, each magnet controlling the other, a battery, circuits to be switched by the pole-changing relay-magnet from one pole of said battery to the other, trunk-lines, and automatic trunk-selecting switches each provided with means for distinguishing between busy and idle trunk-lines, adapted to pass busy trunk-lines, and stop on the first idle trunk-line.

73. The combination, in an automatic telephone trunking system, of a connector provided with a pair of differential-relays, a release-circuit adapted to be closed by the energization of either relay, a private-magnet and a pole-changing-relay each controlled by the other, a battery, circuits to be switched by the pole-changing-relay from one pole of said battery to the other, trunk-lines, and automatic trunk-selecting switches each provided with means for distinguishing between busy and idle trunk-lines, adapted to pass busy trunk-lines and stop on the first idle trunk-line.

74. The combination, in an automatic telephone trunking system, of a pair of line-conductors, a battery having one pole normally connected with both of said conductors, a private-magnet and a pole-changing-relay each controlled by the other, means whereby the energization of the pole-changing-relay switches one line-conductor into connection with the other pole of the battery, trunk-lines, and automatic trunk-selecting switches each provided with means for distinguishing between busy and idle trunk-lines, adapted to pass busy trunk-lines and stop on the first idle trunk-line.

75. The combination, in an automatic telephone trunking system, of a call-signal apparatus comprising a ring-relay, a local circuit for said relay, a pair of relays jointly controlling said circuit, a line-circuit for energizing said pair of relays, together with means by which a called subscriber closes said line-circuit to cause the reenergization of said ring-relay, trunk-lines, and automatic trunk-selecting switches each provided with means for distinguishing between busy and idle trunk-lines, adapted to pass busy trunk-lines and stop on the first idle trunk-line.

76. The combination, in an automatic telephone trunking system, of a calling line, a called line, a ringer-generator, a call-signal circuit including the called line and the

ringer-generator, a busy-signal circuit including the said generator and the calling line, trunk-lines, and automatic trunk-selecting switches each provided with means for distinguishing between busy and idle trunk-lines, adapted to pass busy trunk-lines and stop on the first idle trunk-line.

77. The combination, in an automatic telephone trunking system, of a calling line, a called line, a ringer-generator, a condenser connecting one pole of the generator with the ground, a call-signal circuit including the called line and the generator, a busy-circuit including the condenser and generator and the calling line, trunk-lines, and automatic trunk-selecting switches each provided with means for distinguishing between busy and idle trunk-lines, adapted to pass busy trunk-lines and stop on the first idle trunk-line.

78. The combination, in an automatic telephone trunking system, of a talking circuit, a connector provided with two differential-relays, one a front-bridge-relay, and the other a back-relay, both relays deenergized during use of the circuit for talking purposes, trunk-lines, and automatic trunk-selecting switches each provided with means for distinguishing between busy and idle trunk-lines, adapted to pass busy trunk-lines and stop on the first idle trunk-line, each selecting switch having a release circuit controlled by contacts of said relays.

79. The combination, in an automatic telephone trunking system, of a common battery, a common battery connector, including condensers in the talking conductors thereof, a back differential-relay, a release-circuit controlled by said relay, trunk-lines, and automatic trunk-selecting switches each provided with means for distinguishing between busy and idle trunk-lines, adapted to pass busy trunk-lines and stop on the first idle trunk-line, each selecting switch having a release circuit controlled by contacts of said relay.

80. The combination, in an automatic telephone trunking system, of a connector provided with a release-magnet, release mechanism operated thereby, a plurality of energizing circuits therefor, a differential-relay controlling one of said circuits, another differential-relay controlling the other circuit, trunk-lines, and automatic trunk-selecting switches each provided with means for distinguishing between busy and idle trunk-lines, adapted to pass busy trunk-lines and stop on the first idle trunk-line, each selecting switch including the release circuit controlled by the contacts of said differential relays.

81. The combination, in an automatic telephone trunking system, of a calling and a called line, means for connecting said lines,

means for supplying ringing current to said called line, a ringer-relay for applying the current to the line, an energizing circuit for said relay, said energizing circuit being established independent of the calling line after the connection is completed, an interrupter for intermittently interrupting the flow of current in said circuit, and relay mechanism for removing the ringing current when the called subscriber answers, trunk-lines, and automatic trunk-selecting switches each provided with means for distinguishing between busy and idle trunk-lines, adapted to pass busy trunk-lines and stop on the first idle trunk-line, substantially as and for the purpose set forth.

82. The combination, in an automatic telephone trunking system, of a connector adapted for establishing connection directly with the called subscriber's line, provided with a three-position side-switch, automatic means for locking the side-switch in second position if the called line is busy, trunk-lines, and automatic trunk-selecting switches each provided with means for distinguishing between busy and idle trunk-lines, adapted to pass busy trunk-lines and stop on the first idle trunk-line.

83. In a telephone system, a called subscriber's line, a plurality of connectors by which said line is temporarily seized, means for automatically selecting idle connectors, and automatic means operated when a called line is found for transmitting audible busy-signals through all the connectors except the one first seizing the line.

84. In a telephone system, a called subscriber's line, means for making said line busy, a connector for seizing said line, means for automatically selecting idle connectors, means for preventing the connector from releasing when it seizes the busy line, and automatic means operated when a called line is found for transmitting an audible busy-signal to the calling subscriber to notify him that the said line is already in use.

85. In a telephone system, a called subscriber's line, means for making said line busy, a connector having vertical and rotary motion for seizing said line, the vertical motion for selecting a group and the rotary motion to find a line in the predetermined group, means for preventing the connector from releasing when it seizes the busy line, and automatic means for transmitting an audible busy-signal to the calling subscriber to notify him that the said line is already in use.

86. In a telephone system, the combination of means for automatically trunking one line into connection with another, mechanism including a circuit for signaling the called party, said mechanism operated independent of the calling line after a connection is established, means for restoring said

mechanism to normal when the called party answers, and a condenser in the signaling circuit, the formation of the talking circuit being contingent upon the movement of a switch element in one direction to find a group, and the subsequent movement of the same element in another direction to find a line in the selected group.

87. In a telephone system, an automatic switch for extending connection in the direction of the called party, mechanism including a circuit signaling the called party, said mechanism operated independent of the calling line after a connection is established, means for restoring said mechanism to normal when the called party answers, and a condenser in the signaling circuit, the formation of the talking circuit being contingent upon the movement of a switch element in one direction to find a group, and the subsequent movement of the same element in another direction to find a line in the selected group.

88. In a telephone system, a called subscriber's line, a plurality of connectors by which said line is temporarily seized, means for automatically selecting idle connectors, and automatic means brought into operation after a called line is found for transmitting busy-signals through all the connectors except the one first seizing the line.

89. In a telephone system, a called subscriber's line, means for making said line busy, a connector for seizing said line, means for automatically selecting idle connectors, means for preventing the connector from releasing when it seizes the busy line, and automatic means brought into operation after a called line is found for transmitting a busy signal to the calling subscriber to notify him that the said line is already in use.

90. In a telephone system, a called subscriber's line, means for making said line busy, a connector having vertical and rotary motion for seizing said line, the vertical motion for selecting a group and the rotary motion to find a line in the predetermined group, means for preventing the connector from releasing when it seizes the busy line, and automatic means brought into operation after a called line is found for transmitting a busy signal to the calling subscriber to notify him that the said line is already in use.

91. In a telephone system, a calling subscriber's line, a called subscriber's line, automatic switching apparatus for connecting the calling line with the called line, the said automatic switching apparatus comprising a ringer relay through the medium of which ringing current is supplied to the called subscriber's line, means for taking the ringing current off when the called subscriber answers, an energizing circuit for said relay, means independent of the calling subscriber's control for supplying cur-

rent to said circuit after a connection is established, and an interrupter for intermittently interrupting the flow of current in said circuit, substantially as and for the purpose set forth.

92. In a telephone system, comprising subscriber's lines, progressively movable switching elements through which a connection is established between a calling and a called subscriber's lines, a ringer relay included in one of said switching elements for supplying ringing current to the called subscriber's line, means for taking the ringing current off when the called subscriber answers, an energizing circuit for said relay, means independent of the calling subscriber's control for supplying the current to said circuit after a connection is established, and an interrupter for intermittently interrupting the flow of current in said circuit, substantially as and for the purpose set forth.

93. In a telephone system, comprising subscribers' lines, progressively movable step-by-step switching elements through which a connection is established between a calling and a called subscribers' lines, a ringer relay included in one of said switching elements for supplying ringing current to the called subscriber's line, means for taking the ringing current off when the called subscriber answers, an energizing circuit for said relay, means independently of the calling subscriber's control for supplying the current to said circuit after a connection is completed, and an interrupter for intermittently interrupting the flow of current in said circuit, substantially as and for the purpose set forth.

94. In a telephone system, a called line, connectors for calling said line, means for automatically selecting idle connectors, a busy signaling means normally inaccessible to said connector until a called line is found, means for then making said means accessible to said connector for then transmitting busy signals.

95. In a telephone system, a calling and a called line, automatic progressively movable switching apparatus for connecting the two, said switching mechanism comprising a connector switch, means for signaling the called line from said connector, said means operated independent of the calling line after the connection is established, and means for automatically cutting off the ringing current when the called subscriber answers, releasing apparatus for said switches and for restoring the ringing means when the subscribers are through talking, a circuit for energizing said apparatus, said circuit extending from the connector to the other automatic switching apparatus, said circuit being separate from the talking circuit.

96. In a telephone system, automatic trunk release apparatus for connecting a

calling and a called line, automatic ringing equipment for signaling the called line and means for removing the signaling current when the called subscriber answers, and means for restoring the signaling apparatus to normal controlled over the trunk release circuit, said automatic ringing equipment operated independent of the calling line after the connection is established.

97. In a telephone system, a trunk release first selector and connector for establishing connection between a calling and a called line, automatic ringing equipment in said connector for signaling the called line, said automatic ringing equipment operated independent of the calling line after the connection is established, means for disconnecting the ringing current from the called line when the called subscriber answers, and means for restoring the ringing equipment to normal controlled over the trunk release circuit.

98. In a telephone system, switching apparatus for establishing a talking circuit between a calling and a called line, said apparatus comprising a progressively movable automatic switch, a test circuit associated with said switch, signaling means associated with said switch, means independent of the calling line for operating the same to signal the called line after the called line is found, and means for restoring the said signaling means to normal comprising said test circuit.

99. In a telephone system, automatic switching apparatus for establishing a talking circuit between two lines, said apparatus comprising two switches, ringing equipment and means independent of the calling line for operating the same to signal the called line after the called line is found, releasing means for each of said switches, and a release circuit extending between the switches for operating the said release means to break the connection when the subscribers are through talking and for restoring the signaling means to normal.

100. In a telephone system, switching apparatus for establishing a talking circuit between a calling and a called line, said apparatus comprising a progressively movable automatic switch, a test contact associated with said switch, signaling means associated with said switch, means independent of the calling line for operating the same to signal the called line after the called line is found and for cutting off the ringing current when the called subscriber answers, and means for restoring the said signaling means to normal comprising said test contact.

101. In a telephone system, automatic switching apparatus for connecting calling and called lines, automatic ringing equipment for signaling the called line and a trunk release circuit for controlling said

equipment, means independent of the calling line for operating said equipment to signal the called line after the called line is found.

- 5 102. In a telephone system, a called line, a central source of current for talking purposes, means for making the called line busy, means including a progressively movable switch for finding the called line, and means 10 associated with said first means to retain said switch in its operated position for preventing the called line from being signaled.

- 15 103. In a telephone system, a called line, a central source of current for talking purposes, means for making the called line busy, means including a progressively movable switch for finding the called line, and means in said switch associated with said first means to retain said switch in its operated 20 position for preventing the called line from being signaled.

- 25 104. In a telephone system, a called line, a central source of current for talking purposes, means for making the called line busy, means including a progressively movable switch for finding the called line, and means controlled by said first means to retain said switch in its operated position and to prevent a connection from being extended to 30 said called line.

- 35 105. In a telephone system, a called line, a central source of current for talking purposes, means for making the called line busy, means including a progressively movable switch for finding the called line, and means associated with said first means to retain said switch in its operated position for preventing a circuit from being extended from the switch to a station on the called line.

- 40 106. In a telephone system, a called line, a central source of current for talking purposes, progressively movable switching mechanism for finding said line, means to retain said switching mechanism in its operated position upon finding said line busy.

- 45 107. In a telephone system, a called line, a central source of current for talking purposes, progressively movable switching mechanism for finding said line, and means in said switching mechanism to retain the same in its operated position upon finding said line busy.

- 55 108. In a telephone system, a called line, a central source of current for talking purposes, progressively movable switching mechanism for finding said line, means to retain said switching mechanism in its operated position upon finding said line busy, and means for preventing a connection being 60 completed with said called line.

- 65 109. In a telephone system, a called line, a central source of current for talking purposes, progressively movable switching mechanism for finding said line, and means to retain said switching mechanism in its

operated position upon finding said line busy and for preventing the called line being signaled.

110. In a telephone system, a calling and a called line, a centralized source of current for talking purposes, progressively movable switching mechanism for establishing a connection to the called line, means for making the called line busy, and means for determining the busy condition of the called line 70 and for locking thereon to maintain the connection uncompleted.

111. In a telephone system, a calling and a called line, a centralized source of current for talking purposes, progressively movable switching mechanism for establishing a connection to the called line, means for making the called line busy, and means in said switching mechanism for determining the busy condition of the called line and for 80 locking thereon to maintain the connection 85 uncompleted.

112. In a telephone system, a calling and a called line, progressively movable switching mechanism for establishing a connection 90 to the called line, means for making the called line busy, means for determining the busy condition of the called line and for locking thereon to maintain the connection uncompleted, and means brought into operation after the busy called line is found for transmitting a signal to the calling line.

113. In a telephone system, a calling and a called subscriber's line, automatic switching mechanism for connecting said lines, 100 relays controlled by the called subscriber for supplying the calling subscriber with current for talking purposes, means for making the called line busy, means including one of said relays responsive to the busy condition of the called line for maintaining said switching mechanism in its operated position, and means for giving said calling subscriber a busy signal when the called line is busy.

114. In a telephone system, a called line, means including a test conductor for making the called line busy, means including a progressively movable switch for finding the called line, means associated with said first means to retain said switch in its operated position for preventing the called line being signaled, said last means including a magnet, a circuit over said test conductor for energizing said magnet, and a second circuit 115 for said magnet after it energizes, said second circuit excluding said test conductor.

115. In a telephone system, a called line, means including a test conductor for making the called line busy, means including a progressively movable switch for finding the called line, means controlled by said first means to retain said switch in its operated position and to prevent a connection from being extended to said called line, said last 125 130

means including a magnet, a circuit over said test conductor for energizing said magnet, and a second circuit for said magnet after it energizes, said second circuit excluding said test conductor.

116. In a telephone system, a called line, progressively movable switching mechanism for finding said line, means including a test conductor for making said line busy, 10 means coöperating with said first means to retain said switching mechanism in its operated position, said last means including a magnet, a circuit over said test conductor for energizing said magnet, and a second circuit 15 for said magnet after it energizes, said second circuit excluding said test conductor.

117. In a telephone system, a called line, progressively movable switching mechanism for finding said line, means including a test conductor for making said line busy, means coöperating with said first means to retain 20 said switching mechanism in its operated position, means for preventing a connection from being completed with said called line, 25 said last means including a magnet, a circuit over said test conductor for energizing said magnet, and a second circuit for said magnet after it energizes, said second circuit excluding said test conductor.

118. In a telephone system, a calling and a called line, an automatic switch controlled over the calling line for finding the called line, ringing equipment associated with said switch and controlled therethrough, a relay 30 in said equipment for signaling the called line, and means for controlling said ringing equipment from the called line without necessitating the control of the circuit of any magnet energized over the calling line.

119. In a telephone system, a calling and a called line, an automatic switch controlled over the calling line for finding the called line, ringing equipment associated with said switch and controlled there- 40 through, a relay in said equipment for signaling the called line, means for controlling said ringing equipment from the called line, said means not dependent for such control upon affecting the circuit of any magnet 45 energized over the calling line.

120. In a telephone system, a calling and

a called line, an automatic switch controlled over the calling line for finding the called line, line relays for controlling said switch, ringing equipment associated with said 55 switch and controlled therethrough, a relay in said equipment for signaling the called line, means for controlling said ringing equipment from the called line, and means for maintaining said line relays operative 60 after the called subscriber answers.

121. In a telephone system, a calling and a called line, an automatic switch controlled over the calling line for finding the called line, line relays for controlling said switch, 65 ringing equipment associated with said switch and controlled therethrough, a relay in said equipment for signaling the called line, means for controlling said ringing equipment from the called line, and means 70 for maintaining said line relays energized during talking.

122. In a telephone system, a calling and a called line, an automatic switch controlled over the calling line for finding the called 75 line, a line relay for controlling the group electing operation of said switch, ringing equipment associated with said switch and controlled therethrough, a relay in said equipment for signaling the called line, 80 means for controlling said ringing equipment from the called line, and means for maintaining said line relay operative during talking.

123. In a telephone system, a calling and a called line, an automatic switch controlled over the calling line for finding the called line, a line relay for controlling the group electing operation of said switch, ringing equipment associated with said switch and 85 controlled therethrough, a relay in said equipment for signaling the called line, means for controlling said ringing equipment from the called line, and means for maintaining said line relay energized during talking.

Signed by me at Chicago, Cook county, Illinois, this 12th day of April, 1906.

TALBOT G. MARTIN.

Witnesses:

EDWARD D. FALES,
B. D. WILLIS.
